UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed March 28, 1918, Serial No. 225,340. Renewed October 8, 1923.

To all whom it may concern:

Be it known that I, MORRIS P. HOLMES, a citizen of the United States, residing at Claremont, in the county of Sullivan and 5 State of New Hampshire, have invented certain new and useful Improvements in Mining Machines, of which the following is a full, clear and exact specification.

My invention relates to mining machines. 10 It has for its object to provide an improved mining machine equipped with improved and simplified transmission and controlling mechanism whereby the flexibility of operation of the machine is increased. 15 A further object of my invention is to provide an improved transmission mechanism for such a machine equipped with improved means whereby the same mechanism may be utilized in feeding the machine relative 20 to the truck or face or in driving the machine when the same is mounted upon its truck. A still further object of my invention is to provide a mining machine of improved and simplified construction which 25 may be very readily and cheaply manufactured. These and other objects and advantages of my improved construction will, however, hereinafter more fully appear.

In the accompanying drawings I have 30 shown for purposes of illustration one embodiment which my invention may assume in practice.

In these drawings,—

Fig. 1 is a side elevation of my improved 35 machine mounted upon its truck and connected thereto.

Fig. 2 is a plan view of the machine at the face, partially in section, showing the 40 transmission mechanism, the section being taken substantially on line 2-2 of Fig. 1.

Fig. 3 is a detail sectional view taken 45 substantially on line 3-3 of Fig. 2.

Fig. 4 is a diagrammatic view showing the machine unloading from its truck.

Fig. 5 is a diagrammatic illustration of 50 the machine during the starting of a cut from right to left.

Fig. 6 is a diagrammatic illustration of the machine during the cutting across a face 55 from left to right.

Fig. 7 is a diagrammatic view of the machine returning to position upon its truck after the completion of the cut.

In this illustrative construction, I have 60 shown a mining machine of the usual flex-

ibly fed room and pillar type having a frame 1 equipped with the usual forwardly projecting cutter bar 2 and a cutter chain 3 revolving around the bar, the cutter chain being driven from the motor 4 in any well known manner. It will also be observed that the mining machine shown herein is provided with a rear driving sprocket or feed operating member 5 driven from the motor 4 through transmission mechanism, herein after described, and adapted, through the cooperation of suitable guide sprockets 6 and 7 at the rear end of the machine and cooperating alternatively operative guide sprockets 8 at the front end thereof, to feed the machine to the right or left and relative to the work and a flexible feeding member, herein shown in the form of a chain 9, all in a well known manner. As illustrated in Fig. 1, the mining machine is also supported upon a suitable truck including a truck frame 10 mounted upon wheels 11 which are adapted to run on the mine track 12 and have their axles 13 connected together and driven by means of a usual chain and sprocket connection 14, which is itself driven from the machine, as herein-after more fully brought out.

In my improved construction, it will be observed that the armature shaft 15 of the motor 4 is disposed longitudinally of the machine and provided with a beveled gear 16 on its rear end meshing with a larger horizontally disposed beveled gear 17, which is in turn connected to an upright shaft 18, preferably driving the cutter chain driving sprocket (not shown). It will also be observed that in this construction the armature shaft 15 carries a pinion 19 between the beveled gear 16 and the frame 1, and that this pinion meshes with a larger gear 20 carried on a longitudinally disposed shaft 21 located at one side of the axis of the machine and journaled in suitable bearings 22 and 23 in the frame. Attention is also directed to the fact that the upright shaft 18 is also provided with a worm 24 which in turn meshes with a worm gear 25 of substantially the same diameter as the gear 20 and likewise journaled on the shaft 21 but at a point in rear of that gear and rotatable in an opposite direction to the gear 20. By thus spacing apart the gears 20 and 25, it will be observed that it is possible to insert friction clutch mem-

bers 26 and 27 within the peripheries of the gears and operatively connect these clutch members through toggle members 28 to a central reciprocable member 29 splined to the shaft 21 at 30 and reciprocable relative thereto in such a manner as alternatively to cause either the friction members 26 to engage or clutch the gear 25, or the friction members 27, to engage or 10 clutch the gear 20. As shown, this member 29 is operated by means of a controlling member 31 pivoted at 32 upon the frame and in turn pivotally connected at 33 to a rearwardly extending rod 34 which is operatively connected to an arm 35 formed on a change speed controlling lever 36, which in turn extends through a suitable aperture 37 in the rear end of the frame to within convenient reach 15 of an operator. Thus, it will be observed that by manipulating the member 36, the speed and direction of rotation of the shaft 21 may be varied as desired, a slow speed in one direction being obtainable by throwing the clutch member 26 into engagement with 20 the gear 25, while a fast speed in the opposite direction is obtainable by throwing the clutch member 27 into engagement with the gear 20.

Operatively connected to the rear end of 30 the shaft 21 and acting as a controlling mechanism controlling the connection of either the fast or slow speed transmission mechanism above described, is improved cooperating reversing mechanism. As shown, this mechanism is operatively connected to the shaft 21 through a beveled gear 38 carried on the rear end of the latter, which beveled gear constantly meshes with a plurality of cooperating spaced beveled gears 39 and 40 35 rotatably mounted near one end of a transverse shaft 41, herein shown to be journaled in a suitable bearing 42 and another hereininafter described and formed by the sleeve 63 on opposite sides of the rear end of the frame. As shown, of these beveled gears 39 and 40, the beveled gear 39 is provided with a cooperating friction clutch member 43 similar to the clutch member 27, while the beveled gear 40 is provided with a similar 40 cooperating clutch member 44 similar to the clutch member 26, and these several clutch members are connected through toggle members 45, similar to the toggle members 28, to a reciprocating clutch member 46 splined to 45 the shaft 41 at 47 and otherwise similar to the clutch member 29. As illustrated, this member 46 is also reciprocable longitudinally of the shaft by means of a reversing controlling member or lever 48 pivoted at 49 on the frame and extending through a suitable aperture 50 in the rear end of the same so that it may be readily grasped by an operator, the two levers 36 and 48 preferably being conveniently disposed adjacent one 55 another. By the provision of my improved

reversing mechanism, it will be observed that it is thus possible through manipulation of the lever 48 to reverse the direction of rotation of the shaft 41 whenever desired, regardless of the speed or direction of rotation of its driving shaft 21.

Operatively connected to the shaft 21 and controlled through my improved fast or slow speed mechanism and through my improved reversing mechanism, each above described, is my improved mechanism for 75 rotating the feed sprocket 5. As shown, a worm 51 is rotatably mounted intermediate the ends of the shaft 41 and meshes with a suitable worm gear 52 which is carried on a vertical stud 53 and fixed to the feed sprocket 5 so that the latter is rotated whenever the worm 51 is connected to the shaft and rotated thereby through mechanism 80 hereinafter described. It will also be noted that the worm 51 is provided with oppositely disposed sleeve portions 54 and 55, one of which abuts against the hub of the gear 40, while the other is suitably journaled in 85 bearings 56 carried on the frame. As shown, the sleeve 55 is also provided with clutch teeth 57 adapted to engage with cooperating clutch teeth 58 on a reciprocable clutch member 59 splined at 60 to the shaft 41 and having oppositely disposed teeth 61 on its 90 opposite end adapted to mesh with corresponding teeth 62 formed on the inner end of a sleeve 63 journaled at 64 in the frame and having fixedly attached to its outer end a truck driving sprocket 65. As illustrated, the clutch member 59 is reciprocable relative to the shaft 41 by means of a pivoted feed and power truck drive controlling member 66 pivoted at 67 on the frame and having its 95 operating handle extending through a suitable aperture 68 in the rear end of the frame within convenient reach of the operator, this lever preferably, as shown herein, being disposed on the opposite side of the frame from the levers 36 and 48. As shown, the 100 sprocket 65 is herein connected to a suitable sprocket 69 carried on the rear axle 13, by means of a chain connection 70. Through the use of this improved mechanism, it will be observed that by movement of the controlling member 66 in one direction the feed sprocket 5 may be driven from the shaft 41, and that by movement of the controlling member in the opposite direction the truck driving sprocket 65 may be connected to 105 the shaft 41, while each of these members is disconnectable from that shaft when the controlling member assumes the neutral position shown in Fig. 2.

In the operation of my improved construction, it will be understood that the machine is unloaded and sumped in under the coal at one rib, and then fed across the face and withdrawn and reloaded, all through the operation of the feed sprocket on the 110

feed chain 9 in a well known manner and as shown diagrammatically for purposes of illustration in Figs. 4 to 7. In the first of these figures, i. e. Fig. 4, the machine is 5 shown unloading from its truck. In Fig. 5 the machine is shown in full lines at the completion of sumping and in dotted lines in a position such as might be occupied at the beginning of sumping. In view of the fact 10 that the machine may cut in either direction Fig. 6 discloses the machine cutting across a face from left to right. In Fig. 7, the machine is shown returning to position upon the truck preparatory to moving off 15 to another working face. During these various steps it will be observed that when the member 66 is operated to connect the worm 51 to the shaft 41, an operator is enabled, through the controlling lever 36, to 20 vary the speed of rotation of the feed sprocket 5 at will. It will also be observed that through manipulation of the lever 48 the operator is enabled to vary the direction of rotation of this sprocket at will, re- 25 gardless of the speed at which it is rotated. Thus, through the use of the two levers 36 and 48, he is enabled to obtain either a fast or slow feed in one direction, or a fast or slow feed in the opposite direction. Atten- 30 tion is also directed to the fact that the connection of all of this mechanism is controllable by the lever 66. Thus, when the machine is fed, as shown in Fig. 7 into its loaded position upon its truck, the feed 35 chain then being hooked over the abutment 71 in a usual manner, the operator is enabled by the operation of the lever 66 to disconnect the feed member 5 from the shaft 41 and connect the truck driving sprocket 40 65 to that shaft, and thereafter, through the controlling levers 36 and 43 and the transmission mechanism controlled thereby, drive the truck at fast or slow speed in either direction, as desired, without rotating the feed 45 driving member 5. Conversely, when the machine is to be unloaded, the chain 9 then being connected to a jack or other point in advance of the machine in a usual manner, as shown in Fig. 7, the operator is similarly 50 able in one operation to disconnect the truck drive and connect the feed member 5. During these loading and unloading operations, it will of course be evident that the chain 55 70 may be readily applied to or removed from the sprocket 65 and thus rendered operative or inoperative as the latter moves relative to the truck and the rear axle. It will also be observed that after the chain has been dropped over this sprocket 65 during the loading operation, the tension desired to render it most effective may be readily obtained by means of an adjustable stop 72 limiting the rearward movement of the machine relative to the truck. A suitable pivoted latch 72' will then, as shown in

Fig. 1, serve to hold the machine in proper position on the truck.

In the use of my improved construction, it will be observed that all necessity for the provision of any interlocking mechanism between the various controlling devices is entirely eliminated, the operator being able to pass from one feed to the other by a simple movement of the proper operating lever or levers and without danger of damage to the 70 feeding mechanism. It will also be evident that through the use of separate frictions 27 and 26 for the fast and slow feed mechanisms which include the gears 20 and 25, respectively, it is possible, not only to facilitate the manipulation of the controlling mechanism, the lever 36 being movable freely without any necessity for providing an interlock therefor, but also to proportion 75 each friction to its load, and thereby avoid overloading on the fast feed, which is ordinarily about fifteen times the speed of the slow feed. At the same time, it will be observed that through the provision of the reversing mechanism it is also possible to reverse the feed sprocket 5 irrespective of its speed or direction of rotation. It will also be noted that as the clutches 26 and 27 are driven at speeds varying in proportion to 80 their respective loads, it is entirely unnecessary to provide any means for loading the friction clutch 27 in the fast feed transmission, my improved mechanism acting efficiently with equal loading on the fast and slow feed friction clutches 27 and 26. It 85 will also be observed that through my improved construction it is possible not only to feed the machine with the desired flexibility, but also, through the same mechanism, to drive and, by use of the reverse 90 friction, brake the truck from the machine and thus eliminate all necessity for expensive truck driving mechanism upon the rear end of the truck frame, at the same time that the desired flexibility of truck movement is obtained. It will also be noted that it is made possible to run the power truck independently of the feed, or vice versa, through the provision of the controlling mechanism including the controlling member 66 which in one operation disconnects the feed and connects the power truck, or disconnects the power truck and connects the feed. Attention is also directed to the 95 fact that at the same time that these various improvements are obtained, the number of gears and jaw clutches necessary is minimized. Obviously, in the use of my improvement, the motor 4 may be controlled by any suitable controlling mechanism, such as a controller 73 controllable by usual controller handles 74, my improved construction also permitting of an exceedingly commodious provision for the controller 73 and its cooperating resistance 75 in a suitable 100 105 110 115 120 125 130

enclosed chamber 76 disposed at one side of the frame. It will also be observed that in the use of my improvement an electric cable reel 77 may be mounted, as usual, on supports 78 at the rear end of the truck frame and driven from the motor or wheels, as through a rotating friction member 79 journaled at 80 on the frame and itself rotatable through a chain and sprocket connection 81 driven from the rear axle. These and other advantages of my improved construction will, however, be clearly apparent to those skilled in the art.

While I have in this application specifically described one embodiment which my invention may assume in practice, it will be understood that this form of the same is used only for purposes of illustration, and that the invention may be modified and embodied in various other forms without departing from its spirit or the scope of the appended claims.

What I claim as new and desire to secure by Letters Patent is:

25. 1. In a mining mechanism, a wheeled truck adapted to provide a support for a mining machine during transport, a mining machine adapted to be mounted thereon during transport but dismountable therefrom for cutting upon a mine bottom and including a motor, cutting means operable thereby, a truck driving member and transmission means driven by said motor for driving the truck driving member at different speeds, and means for operatively connecting said truck driving member and the wheels of said truck.
30. 2. In a mining mechanism, a wheeled truck adapted to provide a support for a mining machine during transport, a mining machine adapted to be mounted thereon during transport but dismountable therefrom for cutting upon a mine bottom and including a motor, cutting means operable thereby, a truck driving member and transmission means driven by said motor and operative without reversal of the latter to drive the truck driving member in different directions, and means for operatively connecting said truck driving member and the wheels of said truck.
35. 3. In a mining mechanism, a wheeled truck adapted to provide a support for a mining machine during transport, a mining machine adapted to be mounted thereon during transport but dismountable therefrom for cutting upon a mine bottom and including a motor, cutting means operable thereby, a truck driving member and transmission means driven by said motor and operative to drive said truck driving member at different speeds in opposite directions, and means for operatively connecting said truck driving member and the wheels of said truck.

4. In a mining mechanism, a wheeled truck adapted to provide a support for a mining machine during transport, a mining machine adapted to be mounted thereon during transport but dismountable therefrom for cutting upon a mine bottom and including a motor, cutting means operable thereby, a truck driving member and transmission means driven by said motor and operative to drive the truck driving member in opposite directions and at a plurality of speeds in one direction, and means for operatively connecting said truck driving member and the wheels of said truck.

5. In a mining mechanism, a wheeled truck adapted to provide a support for a mining machine during transport, a mining machine adapted to be mounted thereon during transport but dismountable therefrom for cutting upon a mine bottom and including a motor, cutting means operable thereby, a truck driving member and transmission means driven by said motor and operative to drive the truck driving member in opposite directions and at a plurality of speeds in either direction, and means for operatively connecting said truck driving member and the wheels of said truck.

6. In a mining machine, the combination comprising a wheeled truck, a mining machine slideable longitudinally of the latter and having a laterally extending rotatable truck driving member, a motor, and means permitting said motor to drive said truck driving member in opposite directions without reversal of said motor.

7. In a mining machine, the combination comprising a wheeled truck, a mining machine slideable longitudinally of the latter and having a laterally extending rotatable truck driving member, a motor, and means permitting said motor to drive said truck driving member in opposite directions and at different predetermined speeds without changing the operation of the motor.

8. The combination with a mining machine slideable on a mine bottom and including a frame, of truck driving mechanism thereon including a motor and a truck driving member driven thereby, and means thereon between said motor and said member operable independently of motor control to rotate said member at a plurality of speeds in the same direction.

9. The combination with a mining machine slideable on a mine bottom and including a frame, of truck driving mechanism thereon including a motor and a truck driving member driven thereby, and means thereon between said motor and said member operable independently of motor control to rotate said member at a plurality of speeds in the same direction and to rotate the same in the opposite direction.

10. The combination with a mining ma-

- chine slideable on a mine bottom and including a frame, of truck driving mechanism thereon including a motor and a truck driving member driven thereby, and means thereon between said motor and said member operable independently of motor control to rotate said member at a plurality of speeds in either direction.
11. The combination with a mining machine slideable on its bottom on a mine bottom during cutting, of driving mechanism therefor operative to effect feeding thereof during cutting and including a constantly rotating gearing, a truck driving member, and means for selectively connecting a plurality of elements of said gearing to said truck driving member.
12. A mining machine comprising, in combination, a frame carrying cutting mechanism and slideable over a mine bottom during cutting, a truck driving member on said frame adapted for operative connection with truck propulsion means during transport of said machine, a motor on said frame, reduction gearing connected to said motor, and friction clutch mechanism on said frame interposed between said gearing and said truck driving member and disposed coaxially with the latter.
13. A mining machine comprising, in combination, a truck driving member, fast and slow speed reduction gearing therefor on said machine, and a single friction clutch mechanism interposed between the fast and slow speed reduction gearing and said member and operative to connect the former to the latter irrespective of the speed of drive and disposed coaxially with said member.
14. The combination with a mining machine slideable on a mine bottom including a frame, of a truck driving mechanism thereon including a motor, a truck driving member driven thereby, and means for rotating said member in opposite directions including a friction clutch.
15. The combination with a mining machine slideable on a mine bottom including a frame, of a truck driving mechanism thereon including a motor, a truck driving member driven thereby, and means including a friction clutch for rotating said member at different speeds in opposite directions.
16. The combination with a mining machine slideable on a mine bottom and including a frame, of truck driving mechanism thereon including a motor and a truck driving member driven thereby, means thereon for rotating said member at a plurality of speeds in the same direction, and a friction clutch included in said means.
17. The combination with a mining machine slideable on a mine bottom and including a frame, of truck driving mechanism thereon including a motor and a truck driving member driven thereby, means thereon for rotating said member at a plurality of speeds in the same direction and in the opposite direction, and a friction clutch included in said means.
18. The combination with a mining machine slideable on a mine bottom and including a frame, of truck driving mechanism thereon including a motor and a truck driving member driven thereby, means thereon for rotating said member at a plurality of speeds in either direction, and a friction clutch included in said means.
19. In a mining mechanism, a wheeled truck adapted to provide a support for a mining machine during transport, a mining machine adapted to be mounted thereon during transport but dismountable therefrom during cutting upon a mine bottom and including a motor, a truck driving member operatively connectible with the truck wheels and means operative independently of motor control for driving said truck driving member at different speeds or in opposite directions and checking rotation of the same, and means for operatively connecting said truck driving member and said truck wheels.
20. In a mining mechanism, a wheeled truck adapted to provide a support for a mining machine during transport, a mining machine adapted to be mounted thereon during transport but dismountable therefrom during cutting upon a mine bottom and including a motor, a truck driving member operatively connectible with the truck wheels and means for driving said truck driving member at different speeds or in opposite directions and checking rotation of the same without reversal of the motor, and means for operatively connecting said member and the wheels of said truck.
21. The combination, in a mining machine slideable on a mine bottom and including a frame, of truck driving mechanism thereon including a motor, a truck driving member, and operatively connected means for rotating said member by power from said motor and for frictionally retarding the rotation of said truck driving member.
22. In a mining apparatus, a mining machine truck, a mining machine slideable thereover during loading and unloading, a flexible truck driving connection between said machine and truck, and means between said machine and truck for insuring proper tensioning of said flexible driving connection including a pivoted latch on said machine and a cooperating latch engaging member on said truck.
23. In a mining machine slideable over a mine bottom during cutting, a motor having a power shaft rotatable on an axis extending longitudinally of said machine, a shaft parallel to said power shaft and driven directly thereby, a transversely disposed shaft, bevel

- driving gearing between said second and third mentioned shafts and directly connecting the same, and a truck driving member coaxial with the third mentioned shaft and rotatable thereby.
24. In combination, a mining machine having a longitudinally extending motor shaft, carrying at one end thereof a bevel gear and a spur gear, a vertically disposed shaft carrying a bevel gear driven by said first mentioned bevel gear, a shaft parallel to said motor shaft provided with a gear driven by said spur gear, a truck driving member rotatable on a transverse axis and operatively connected with said third mentioned shaft, a wheeled truck adapted to receive said mining machine, and operative driving connections between said truck driving member and the wheels of said truck.
25. In combination, in a mining machine, a motor having a power shaft rotating on a longitudinally extending axis, a plurality of driving elements on said motor shaft at one end thereof, cutting mechanism driven by the element more remote from said motor, a transversely disposed shaft operatively connected with the element nearer the motor, and a truck driving member adapted for actuation by said transverse shaft.
26. In a mining machine slidable over a mine bottom during cutting, a motor having a power shaft rotatable on an axis extending longitudinally of said machine and midway between the sides thereof, a shaft parallel to the said power shaft and driven directly thereby, a transversely disposed shaft, bevel driving gearing between said second and third mentioned shafts and directly connecting the same, and a truck driving member coaxial with the third mentioned shaft and rotatable thereby.
27. In a mining machine slidable over a mine bottom during cutting, a motor having a power shaft rotatable on an axis extending longitudinally of said machine and midway between the sides thereof, a shaft parallel to said power shaft and driven directly thereby and disposed nearer one side of said machine than said power shaft, a transversely disposed shaft, bevel driving gearing between said second and third mentioned shafts and directly connecting the same, and a truck driving member coaxial with the third mentioned shaft and rotatable thereby.
28. In combination, a mining machine, a motor having a power shaft rotating on a longitudinally extending axis, a plurality of driving elements on said motor shaft at one end thereof, the outer one of said elements being a bevel pinion, cutting mechanism driven by the element more remote from said motor including a vertical shaft having a bevel gear meshing with said bevel pinion, a transversely disposed shaft operatively connected with the element nearer the motor, and a truck driving member adapted for actuation by said transverse shaft.
29. In a mining machine slidable over a mine bottom during cutting, a machine frame, feeding mechanism thereon, truck driving mechanism thereon, and common driving mechanism for both of said previously mentioned mechanisms including change speed gearing for varying the speed of either mechanism.
30. A mining machine slidable over a mine bottom during cutting including a machine frame, feeding mechanism thereon adapted to cooperate with flexible feeding means, truck driving mechanism thereon, and common driving mechanism for both of said previously mentioned mechanisms including reverse gearing for controlling the direction of movement of either mechanism.
31. A mining machine slidable over a mine bottom during cutting including a machine frame, feeding mechanism thereon adapted to cooperate with flexible feeding means, truck driving mechanism thereon, and common driving mechanism for both of said previously mentioned mechanisms including mechanical reverse and speed changing gearing adapted to cooperate with either of said first two mechanisms.
32. A mining machine slidable over a mine bottom during cutting including a machine frame, feeding mechanism thereon including a feed operating member adapted to cooperate with flexible feeding means, a truck driving member on said frame, variable speed transmission mechanism on said frame, and means for selectively driving either of said members through said mechanism.
33. A mining machine slidable over a mine bottom during cutting including a machine frame, feeding mechanism thereon including a feed operating member adapted to cooperate with flexible feeding means, a truck driving member on said frame, transmission means on said frame including a reversing mechanism, and means for selectively driving either of said members through the latter.
34. A mining machine slidable over a mine bottom during cutting including a machine frame, feeding mechanism thereon including a feed operating member adapted to cooperate with flexible feeding means, a truck driving member on said frame, and transmission means on said frame including a reversing and speed varying mechanism and means also on said frame for selectively connecting said members to said reversing and speed varying mechanism.
35. A mining machine slidable over a mine bottom during cutting including a machine frame, feeding mechanism thereon including a feed operating member adapted to cooperate with flexible feeding means, a truck driv-

- ing member on said frame, cutting mechanism on said frame, driving mechanism for said cutting mechanism, combined feeding and truck driving mechanism branching from said cutting mechanism driving mechanism, and means for at will connecting either member to said combined feeding and truck driving mechanism.
36. In a mining machine, a frame, a rotatable feed operating member on said frame, a rotatable truck driving member thereon, and common mechanism for rotating either of said members including independently operable mechanical speed changing and reversing gearings.
37. In a mining machine, a frame, cutting mechanism projecting therefrom, a rotatable feeding member on said frame, a rotatable truck driving member thereon, and rotating mechanism for either of said members including a reversible speed changing clutch and a reversing clutch operable one independently of the other.
38. The combination with a mining machine slideable on its bottom on a mine bottom, of fast and slow speed drive trains thereon driven from a common source, feed and truck driving members on said machine, and means between said trains and members for connecting one of said members with either train and the other with one of said trains.
39. The combination with a mining machine slideable on its bottom on a mine bottom, of fast and slow speed drive trains thereon driven from a common source, feed and truck driving members on said machine, and means between said trains and members for connecting either of said members with either train.
40. In a mining apparatus, a machine frame, a feed operating member thereon adapted to effect feeding thereof over a mine bottom, a truck driving member thereon adapted to effect propulsion thereof about a mine when mounted on a truck, and common driving mechanism for said feeding and truck driving members including a motor and means for separately controlling the speed and direction of movement of one of the first two members between said members and said motor.
41. In a mining machine, a machine frame, feeding mechanism thereon, truck driving mechanism thereon, mechanical variable speed mechanism operative to drive either of said mechanisms previously mentioned at different predetermined speeds, and controlling mechanism operative to control both said feeding and truck driving mechanisms.
42. The combination with a mining machine, of a feed operating member thereon, a truck driving member thereon, a motor, reduction mechanism therefor, and means for selectively connecting different elements of said reduction mechanism to either of said members to drive the latter at a plurality of predetermined speeds.
43. The combination with a mining machine slideable on a mine bottom during cutting and fed and guided by flexible machine feeding portions, of driving mechanism therefor including a constantly rotating gearing, a feed operating member, a truck driving member, and means for selectively connecting a plurality of elements of said gearing to said feed operating member or to said truck driving member.
44. The combination with a mining machine, of a feed operating member thereon, a truck driving member thereon, a motor and transmission mechanism thereon for said feed operating member including elements operable selectively to drive said truck driving member reversely at variable speed and check the rotation of the same.
45. The combination with a mining machine slideable on its bottom on a mine bottom, of a motor, reduction gearing driven thereby, a feed operating member, a truck driving member, and means for selectively connecting either of said members to said gearing for rotation thereby at different predetermined speeds.
46. The combination with a mining machine slideable on its bottom on a mine bottom, of a motor, reduction gearing driven thereby, a feed operating member, a truck driving member, and means including a plurality of clutches for selectively connecting either of said members thereto for rotation thereby at different predetermined speeds.
47. In a mining machine, a machine frame, cutting mechanism projecting therefrom, a feed operating element, a truck driving element, common driving means for said feed operating and truck driving elements including variable speed transmission mechanism, and means permitting variation of the speed of the truck driving element independently of the feeding element.
48. In a mining machine, a machine frame slideable over a mine bottom during cutting, cutting mechanism projecting therefrom, a feed operating element adapted to cooperate with flexible feeding means to effect propulsion of said machine during cutting, a truck driving element, common driving means for said feed operating and truck driving elements including truck reversing transmission mechanism, and means on said truck permitting reversal of the truck driving element independently of the feeding element.
49. In a mining machine, a machine frame, cutting mechanism projecting therefrom, a feed operating element, a truck driving element, common driving means for

said feed operating and truck driving elements including common reversing and speed varying transmission mechanism, and means permitting reversal and variation in the speed of said truck driving element independently of said feeding element.

50. In a mining machine, a machine frame 10 slidable over a mine bottom during cutting, a feed operating member thereon adapted to cooperate with flexible feeding means in the feeding and guiding of said frame, a truck driving member on said frame, combined feeding and truck driving mechanism on said frame, and means having only a 15 single controlling member for disconnecting the feed operating member from said mechanism and in the same operation connecting the truck driving member thereto.

51. In a mining machine, a machine frame 20 slidable over a mine bottom during cutting, a feed operating member thereon adapted to cooperate with flexible feeding means in the feeding and guiding of said frame, a truck driving member on said frame, combined 25 feeding and truck driving mechanism on said frame, and means having only a single controlling member for disconnecting the truck driving member from said mechanism and in the same operation connecting the 30 feed operating member thereto.

52. In a mining machine, a machine frame 35 slidably over a mine bottom during cutting, a motor, a feed operating member on said frame adapted to cooperate with flexible feeding means in the feeding of said machine, a truck driving member, variable speed reversible driving means operatively connected to said motor and constituting common driving means for said feed operating 40 member and truck driving member, and means for selectively connecting said members thereto.

53. In a mining machine, a machine frame 45 slidable over a mine bottom during cutting, a feed operating member thereon adapted to cooperate with flexible feeding means in the feeding and guiding of said frame, a truck driving member on said frame, combined feeding and truck driving mechanism 50 on said frame, and means having only a single controlling member for at will disconnecting one of said members and connecting the other or connecting the former and disconnecting the latter relative to said 55 combined mechanism.

54. The combination with a mining machine, of a feed operating member thereon, a truck driving member thereon, and frictional driving mechanism thereon for said 60 feed operating member including elements operable selectively to drive reversely at variable speed and frictionally check the rotation of said truck driving member.

55. The combination with a mining machine, of feed driving mechanism including

reduction gearing, a feed operating member, a truck driving member, and operative connections between the same including a plurality of clutches, one operable to vary the speed of drive of either of said members. 70

56. In a mining machine, a machine frame 75 slidable over a mine bottom during cutting, a feed operating member thereon adapted to cooperate with flexible feeding means in the feeding and guiding of said frame, a truck driving member on said frame, combined feeding and truck driving mechanism on said frame, and means for disconnecting said feed operating member therefrom automatically operative on movement to effect 80 such disconnection and to connect the truck driving member thereto.

57. In a mining machine, a machine frame 85 slidable over a mine bottom during cutting, a feed operating member thereon adapted to cooperate with flexible feeding means in the feeding and guiding of said frame, a truck driving member on said frame, combined feeding and truck driving mechanism on said frame, and means for disconnecting 90 the truck driving member therefrom and automatically operative on continued movement in a direction to effect such disconnection to connect the feed operating member thereto. 95

58. In a mining machine slidable over a mine bottom during cutting, a feed operating member adapted to effect propulsion of said machine during cutting, a truck driving member on said machine, a motor, reduction gearing including a gear having a feeding speed, and means for connecting either member to said gear disconnecting it therefrom. 100

59. In a mining machine slidable over a mine bottom during cutting, a feed operating member adapted to effect propulsion of said machine during cutting, a truck driving member on said machine, a motor, reduction gearing including a gear having a feeding speed, and friction means for connecting 105 either member to said gear. 110

60. In a mining machine slidable over a mine bottom while cutting, feeding and truck driving mechanisms on said machine for respectively feeding the machine over the mine bottom and propelling the same about a mine when mounted upon a truck, and frictional controlling mechanism on said machine which is operative to control either said feeding or said truck driving mechanism. 115 120

61. In a mining machine slidable over a mine bottom while cutting, feeding and truck driving mechanisms on said machine for respectively feeding the machine over the mine bottom and propelling the same about a mine when mounted upon a truck, and frictional means on said machine for reversing either said feeding or said truck driving mechanism. 125 130

62. In combination, in a mining machine, a machine frame slidable over a mine bottom during cutting, feeding mechanism thereon adapted to cooperate with flexible feeding means in the propulsion of the machine during cutting, truck driving mechanism on said frame, and frictional means on said machine which is operable to effect variation in the speed of either said feeding or said truck driving mechanism.

63. The combination with a mining machine, of feeding mechanism thereon, truck driving mechanism thereon, and frictional means thereon for reversing and varying the speed of either said feeding or said truck driving mechanism.

64. The combination with a mining machine, of feeding mechanism thereon, truck driving mechanism thereon, and means thereon constituting common driving mechanism for said feeding mechanism and for said truck driving mechanism and including a plurality of separate friction devices each for controlling either said feeding or said truck driving mechanism.

65. The combination with a mining machine slidable on a mine bottom during cutting, of a feed operating member thereon, a truck driving member thereon, frictional driving mechanism thereon and constituting common driving mechanism for said feed operating member and for said truck driving member, and means for selectively connecting said members to said driving mechanism.

66. In combination, in a mining machine operative to slide upon a mine bottom during cutting, a machine frame, a feed operating member on said frame for propelling the latter, a truck driving member thereon, frictional driving means thereon including a frictional reversing mechanism and constituting common driving mechanism for said feed operating member and for said truck driving member, and means thereon for selectively connecting said members to the latter.

67. The combination comprising a mining machine adapted during cutting to slide directly on a mine bottom, a feed operating member thereon, a truck driving member thereon, frictional driving means thereon including a friction controlled multi-speed mechanism and constituting common driving mechanism for said feed operating member and for said truck driving member, and means thereon for selectively connecting said members to the latter.

68. The combination comprising a mining machine, a feed operating member thereon, a truck driving member thereon, frictional driving means thereon including a frictional reversing and speed varying mechanism and constituting common driving mechanism for said feed operating member and for said

truck driving member, and means thereon for selectively connecting said members to the latter.

69. The combination with a mining machine, of a feed operating member, a truck driving member, driving mechanism selectively operable to drive either of said members at different predetermined speeds including a motor and plural predetermined speed gearing, and means for enabling either of said members to transmit equal maximum torques at different speeds.

70. In combination, in a mining machine, a motor, a feed operating member, a truck driving member, variable speed driving mechanism driven by said motor and operative selectively while said motor speed remains constant to effect driving at a plurality of predetermined speeds, and means for selectively connecting said members to said driving mechanism for drive thereby including means between said mechanism and said members for enabling one of said members to transmit equal maximum torques at different speeds.

71. In combination, in a mining machine, a motor, a feed operating member, a truck driving member, variable speed driving mechanism driven by said motor and operative selectively while said motor speed remains constant to effect driving at a plurality of predetermined speeds, and means including a positive clutch and a friction clutch for selectively driving either of said members from said driving mechanism at a plurality of different speeds.

72. In a mining machine slidable over a mine bottom during cutting, a machine frame, a motor thereon, motor driven feeding mechanism thereon adapted to cooperate with flexible feeding means in the feeding of said machine over a mine bottom and including variable speed driving and controlling mechanism, and truck driving mechanism on said frame also driven by said variable speed driving and controlling mechanism.

73. In a mining machine slidable over a mine bottom during cutting, a machine frame, a motor thereon, motor driven feeding mechanism thereon adapted to cooperate with flexible feeding means in the feeding of said machine over a mine bottom and including reversible driving and controlling mechanism, and truck driving mechanism on said frame also driven by said reversible driving and controlling mechanism.

74. In a mining machine, the combination comprising a machine frame, feeding mechanism thereon including feed operating means, a motor and transmission means actuated by said motor for controlling the speed and direction of movement of said feed operating means and operative to effect rotation thereof at a plurality of predetermined speeds, and a truck driving member.

driven by and controlled by said transmission means.

75. In combination, in a mining machine, a machine frame, a feed operating member thereon, a truck driving member thereon, a motor, plural predetermined speed reduction gearing between said motor and said feed operating member, and means for driving said truck driving member from said gearing at a plurality of predetermined speeds.

76. In a mining machine, a machine frame 15 slidable over a mine bottom, a feed operating member thereon adapted to cooperate with flexible feeding means in the feeding of said machine, a truck driving member thereon, a motor, transmission gearing including reversing mechanism between said motor and said feed operating member, and means for driving said truck driving member from said transmission mechanism in either direction.

77. In combination with a mining machine, a machine frame slidable on a mine bottom, feeding mechanism on said frame adapted to cooperate with flexible feeding means in the feeding thereof and rotatable at a plurality of speeds in one direction and at a plurality of speeds in the opposite direction, and truck driving mechanism on said frame rotatable by said feeding mechanism at one of said speeds.

78. In combination with a mining machine, a machine frame slidable on a mine bottom, feeding mechanism on said frame 25 adapted to cooperate with flexible feeding means in the feeding thereof and rotatable at a plurality of speeds in one direction and at a plurality of speeds in the opposite direction, and truck driving mechanism on said frame rotatable by said feeding mechanism at a plurality of speeds in one direction and in the opposite direction.

79. In combination with a mining machine, a machine frame slidable on a mine bottom, feeding mechanism on said frame 45 adapted to cooperate with flexible feeding means in the feeding thereof and rotatable at a plurality of predetermined geared speeds in one direction and at a plurality of predetermined geared speeds in the opposite direction, and truck driving mechanism on said frame rotatable by said feeding mechanism at any of said speeds in one direction and in the opposite direction.

80. In a mining machine, a machine frame 60 slidable upon a mine bottom during cutting, cutting mechanism thereon, feeding mechanism also thereon including a feed operating member adapted to cooperate with flexible feeding means in the feeding and guiding of the machine and a train having, as regards cutting mechanism actuation, a purely feed operating and controlling function and driving mechanism for said train,

and truck driving mechanism on said frame driven by an element of said train.

81. In a mining machine, a machine frame 70 slidable upon a mine bottom during cutting, cutting mechanism thereon, feeding mechanism also thereon including a feed operating member adapted to cooperate with flexible feeding means in the feeding and guiding of the machine and a train having, as regards cutting mechanism actuation, a purely feed operating and controlling function and driving mechanism for said train, and truck driving mechanism on said frame driven by an element of said train, said train including therein nearer the source of power 80 than said element multi-speed gearing.

82. In a mining machine, a machine frame 85 slidable upon a mine bottom during cutting, cutting mechanism thereon, feeding mechanism also thereon including a feed operating member adapted to cooperate with flexible feeding means in the feeding and guiding of the machine and a train having, as regards cutting mechanism actuation, a purely feed operating and controlling function and driving mechanism for said train, and truck driving mechanism on said frame driven by an element of said train, said train including therein nearer the source of power 90 than said element multi-speed gearing.

83. In a mining machine, a machine frame 95 slidable upon a mine bottom during cutting, cutting mechanism thereon, feeding mechanism also thereon including a feed operating member adapted to cooperate with flexible feeding means in the feeding and guiding of the machine and a train having, as regards cutting mechanism actuation, a purely feed operating and controlling function and driving mechanism for said train, and truck driving mechanism on said frame driven by an element of said train, said train including therein nearer the source of power 100 than said element multi-speed and reversing gearing.

84. In a mining machine, a machine frame 110 slidable over a mine bottom during cutting, cutting mechanism carried thereby, feeding mechanism also carried thereby and adapted to cooperate with flexible feeding means in the feeding and guiding of said machine, driving mechanism for said feeding mechanism having, as regards cutting mechanism actuation, a purely feed operating function and driving means for said driving mechanism, truck driving mechanism on said frame driven by said feed driving mechanism, and controlling mechanism for said feeding mechanism and for said truck driving mechanism.

85. In a mining machine, a machine frame 115 slidable over a mine bottom during cutting, cutting mechanism thereon, means for feeding and guiding the same including flexible feeding means and feeding mechanism 120 cooperating therewith and arranged on said 125

frame and including a train having, as regards cutting mechanism actuation, a purely feed operating and controlling function and driving mechanism for said train, and truck driving mechanism on said frame driven by an element of said train, said train including means for checking the rotation of said truck driving mechanism.

86. In a mining machine, a machine frame, 10 slidable over a mine bottom during cutting, cutting mechanism thereon, means for feeding and guiding the same including flexible feeding means and feeding mechanism co-operating therewith and arranged on said frame and including a train having, as regards cutting mechanism actuation, a purely feed operating and controlling function and driving mechanism for said train, and truck driving mechanism on said frame driven by an element of said train, said train including means for reversing or checking the rotation of said truck driving mechanism.

87. In a mining machine, a machine frame slidable over a mine bottom during cutting, cutting mechanism thereon, means for feeding and guiding the same including flexible feeding means and feeding mechanism co-operating therewith and arranged on said frame and including a train having, as regards cutting mechanism actuation, a purely feed operating and controlling function and driving mechanism for said train, and truck driving mechanism on said frame driven by an element of said train, said train including means for changing the speed of or checking the rotation of said truck driving mechanism.

88. In a mining machine, a machine frame slidable over a mine bottom during cutting, cutting mechanism thereon, means for feeding and guiding the same including flexible feeding means and feeding mechanism co-operating therewith and arranged on said frame and including a train having, as regards cutting mechanism actuation, a purely feed operating and controlling function and driving mechanism for said train, and truck driving mechanism on said frame driven by an element of said train, said train including means for reversing, changing the speed, or checking the rotation of said truck driving mechanism.

89. In a mining machine, a machine frame slidable over a mine bottom during cutting, cutting mechanism thereon, means for feeding and guiding the same including flexible feeding means and feeding mechanism co-operating therewith and arranged on said frame and including a train having, as regards cutting mechanism actuation, a purely feed operating and controlling function and driving mechanism for said train, and truck driving mechanism on said frame driven by an element of said train, said train including means for checking the rotation of said truck driving mechanism irrespective of the direc-

tions of rotation of the elements of said train.

90. In a mining machine, a machine frame, feeding mechanism thereon including a feed operating member rotating on a vertical axis and driving mechanism for the latter including a motor and power transmission connections between the motor and said feed operating member for transmitting power to the latter, said power transmission connections including a transversely extending shaft, and truck driving mechanism driven from said transversely extending shaft.

91. In a mining machine, a machine frame, feeding mechanism thereon including a feed operating member and driving mechanism for the latter including a motor and power transmission connections between the motor and said feed operating member for transmitting power to the latter, said power transmission connections including a transversely extending shaft, and truck driving mechanism driven from said transversely extending shaft at two predetermined speeds.

92. In a mining machine, a machine frame, feeding mechanism thereon including a feed operating member rotating on an axis midway between the sides of the machine frame and driving mechanism for the latter including a motor and power transmission connections between the motor and said feed operating member, said power transmission connections including a transversely extending shaft, and plural predetermined speed power transmission gearing between said shaft and motor and truck driving mechanism driven from said transversely extending shaft.

93. In a mining machine, a machine frame, feeding mechanism thereon including a feed operating member and driving mechanism for the latter including a motor and power transmission connections between the motor and said feed operating member, said power transmission connections including a transversely extending shaft and plural predetermined speed power transmission gearing between said shaft and motor, and truck driving mechanism driven from said transversely extending shaft and including a truck driving element coaxial with said shaft.

94. In a mining machine, a machine frame, feeding mechanism thereon including a feed operating member and driving mechanism for the latter including a motor and power transmission connections between the motor and said feed operating member, said power transmission connections including a transversely extending shaft and plural predetermined speed power transmission gearing between said shaft and motor, and truck driving mechanism driven from

said transversely extending shaft and including a truck driving element coaxial with said shaft and means for clutching the same thereto.

- 5 95. In a mining machine, a machine frame, feeding mechanism thereon including a feed operating member and driving mechanism for the latter including a motor and power transmission connections between the motor and said feed operating member, 10 said power transmission connections including a transversely extending shaft and plural predetermined speed power transmission gearing between said shaft and motor and truck driving mechanism driven from said transversely extending shaft and including a truck driving element rotating on an axis parallel to a line which is parallel to said shaft and means for connecting said shaft in driving relation to said truck driving element.

- 20 96. In a mining machine, a machine frame, cutting mechanism projecting therefrom, a rotatable feeding member on said frame, 25 driving mechanism operatively connectible to said member to transmit power thereto including a transverse shaft, a rotatable truck driving member carried on said shaft, and friction clutch mechanism included in said driving mechanism and controlling the rotation of said truck driving member.

- 30 97. In a mining machine, a machine frame, cutting mechanism projecting therefrom, a motor, a rotatable feeding member on said frame, 35 driving mechanism operatively connectible to said member to transmit power thereto including a transverse shaft, a truck driving member carried on said shaft, and mechanism included in said driving mechanism for effecting driving of said truck driving member in opposite directions.

- 40 98. In a mining machine, a machine frame, cutting mechanism projecting therefrom, a rotatable feeding member on said frame, 45 driving mechanism operatively connectible to said member to transmit power thereto including a transverse shaft, a truck driving member carried on said shaft, and mechanism included in said driving mechanism and controlling the speed of said truck driving member.

- 45 99. In a mining machine, a machine frame, cutting mechanism projecting therefrom, a rotatable feeding member on said frame, 55 driving mechanism connected to said member to transmit power thereto including a transverse shaft, a truck driving member carried on said shaft, and mechanism included in said driving mechanism and controlling the speed and direction of rotation of said truck driving member.

- 55 100. In a mining machine, a frame, cutting mechanism projecting therefrom, a rotatable feeding member, driving mechanism

connected to said member to transmit power thereto including a transverse shaft, a truck driving member carried on said shaft, and mechanism operable at will to control the speed and direction of rotation of either 70 said feeding member or said truck driving member.

101. In a mining machine, a frame, cutting mechanism thereon, a transverse shaft journaled on said frame, combined feeding 75 and truck drive plural predetermined speed transmission mechanism operatively connectible to said shaft to drive the same, feed operating and truck driving members operatively connected to said shaft, and controlling mechanism controlling the connection of one of said members to said shaft.

102. In a mining machine, a frame, cutting mechanism projecting therefrom, a rotatable feeding member, driving mechanism 85 connected to said member including a transverse shaft, a truck driving member carried on said shaft, mechanism operable at will to control the speed and direction of rotation 90 of either said feeding member or said truck driving member, and independently operable means controlling the connection of said driving member to said shaft.

103. In a mining machine, a frame, cutting mechanism projecting therefrom, a rotatable feeding member, driving mechanism 95 connected to said member including a transverse shaft, a truck driving member carried on said shaft, mechanism operable at will to control the speed and direction of rotation 100 of either said feeding member or said truck driving member, and independently operable means controlling the connection of said driving member or said feeding member to said shaft.

104. In a mining machine, a frame, cutting mechanism thereon, a transverse shaft journaled on said frame, combined feeding and truck drive transmission mechanism 110 operatively connectible to said shaft to drive the same, feed operating and truck driving members operatively connected to said shaft for driving thereby, and mechanism including a plurality of controlling members controlling the speed and direction of rotation 115 of the latter.

105. In a mining machine, a machine frame, cutting mechanism projecting therefrom, a rotatable feeding member on said frame, 120 driving mechanism operatively connectible to said member to drive the same including a transverse shaft, a truck driving member carried on said shaft, and independently operable mechanisms controlling the speed and direction of rotation of said truck driving member.

106. In a mining machine, a machine frame, and truck driving mechanism thereon including a truck driving member projecting laterally therefrom and rotating on a 130

transverse axis, a supporting and driving shaft therefor, a bevel gear on said shaft, and driving means for said bevel gear including a second shaft rotating on an axis perpendicular to said first mentioned shaft and carrying a bevel pinion meshing with said bevel gear and a coaxial worm wheel, and a power driven worm meshing with said worm wheel.

107. In a mining machine, a machine frame, and truck driving mechanism thereon including a truck driving member projecting laterally therefrom and rotating on a transverse axis, a supporting and driving shaft therefor, a bevel gear on said shaft, and driving means for said bevel gear including a second shaft rotating on an axis perpendicular to said first mentioned shaft and carrying a bevel pinion meshing with said bevel gear and a worm wheel coaxial with said pinion, and a power driven worm meshing with said worm wheel and rotating on an axis perpendicular to a line parallel to the axis of rotation of said truck driving member.

108. In a mining machine, a machine frame, truck driving mechanism thereon including a truck driving member projecting laterally therefrom and rotating on a transverse axis, a supporting and driving shaft therefor, a bevel gear on said shaft, and driving means for said bevel gear including a second shaft rotating on an axis perpendicular to said first mentioned shaft and carrying a bevel pinion meshing with said bevel gear and a worm wheel coaxial with said pinion, and a power driven worm meshing with said worm wheel, and feeding mechanism for said mining machine including a feed operating member adapted to cooperate with a flexible feeding member in the feeding of said machine upon a mine bottom and driving connections between one of said shafts and said feed operating member.

109. In a mining machine, a machine frame, truck driving mechanism thereon including a truck driving member projecting laterally therefrom and rotating on a transverse axis, a supporting and driving shaft therefor, a bevel gear on said shaft, and driving means for said bevel gear including a second shaft rotating on an axis perpendicular to said first mentioned shaft and carrying a bevel pinion meshing with said bevel gear and a worm wheel co-axial with said pinion, and a power driven worm meshing with said worm wheel, and feeding mechanism for said mining machine including a feed operating member adapted to cooperate with a flexible feeding member in the feeding of said machine upon a mine bottom and driving connections including speed reduction mechanism between one of said shafts and said feed operating member.

110. In a mining machine, a machine frame, truck driving mechanism thereon including a truck driving member projecting laterally therefrom and rotating on a transverse axis, a supporting and driving shaft therefor, a bevel gear on said shaft, and driving means for said bevel gear including a second shaft rotating on an axis perpendicular to said first mentioned shaft and carrying a bevel pinion meshing with said bevel gear and a worm wheel co-axial with said pinion, and a power driven worm meshing with said worm wheel, and feeding mechanism for said mining machine including a feed operating member adapted to cooperate with a flexible feeding member in the feeding of said machine upon a mine bottom, and operator controlled driving connections between one of said shafts and said feed operating member.

111. In a mining machine, the combination with feeding means, of actuating mechanism therefor including a shaft, a motor, means actuated by said motor and operative while said motor continues to rotate in one direction at uniform speed to rotate said shaft at a plurality of speeds and in either direction including, means for simultaneously controlling the speed and direction of rotation of said shaft, a second shaft, and reversing gearing connecting said shafts through which said first mentioned shaft may drive said second mentioned shaft.

112. In a mining machine, the combination with feeding means, of actuating mechanism therefor including a shaft, means operative to rotate said shaft at a plurality of speeds and in either direction including, means for simultaneously controlling the speed and direction of rotation of said shaft, a beveled gear on said shaft, a second shaft, and a plurality of beveled gears on said second shaft alternatively operative as driving elements for second shaft and meshing with said first named beveled gear.

113. The combination with a rotatable feed operating member, of friction driving mechanism therefor including a pair of friction clutches selectively operative to drive the same in opposite directions at different predetermined speeds, and a supplemental clutch mechanism for controlling the direction of feed.

114. The combination with a rotatable feed operating member, of friction driving mechanism therefor including a pair of friction clutches selectively operative to drive the same in opposite directions at different predetermined speeds, and a supplemental independently operable clutch mechanism controlling the direction of feed and disposed between said friction clutches and said feed operating member.

115. A mining machine slideable on a mine bottom comprising a machine frame, flexible

- operative connections between the same and said first named feeding shaft, independent means for operating each of said friction mechanisms, independent means for controlling the connection of said feeding member to said transverse shaft, and a truck driving member connectable with said shaft.
124. In a mining machine, a frame, cutting mechanism projecting therefrom, a motor on said frame having a longitudinally disposed armature shaft, a parallel feed shaft, a vertical shaft operatively connected to said armature shaft, friction controlled speed changing connections operatively connected between both said vertical shaft and armature shaft and said feed shaft, a rotatable feeding member on said frame, a transverse feeding shaft operatively connectable therewith, reversible friction controlled operative connections between the same and said first named feeding shaft, independent means for operating each of said friction mechanisms, independent means for controlling the connection of said feeding member to said transverse shaft, and a truck driving member connectable with said shaft and controlled by said last mentioned controlling mechanism.
125. In a room and pillar mining machine having fixedly projecting cutting mechanism and slideable directly on a mine bottom, a driving motor operatively connected to the cutting mechanism, machine feeding and guiding mechanism including a plurality of flexible feeding portions each having a free extremity and extending laterally from opposite ends of said machine, and means driven by said motor for winding in either of said portions including power transmission connections including a plurality of friction clutches selectively operative to reverse the direction of feed without reversal of the motor, feed controlling mechanism for selectively actuating said clutches to effect feed in opposite directions, and supplemental means for further modifying the feed and located in said power transmission connections at the opposite side of said clutches from the motor.
126. In a room and pillar mining machine having projecting cutting mechanism and slideable on a mine bottom, a driving motor operatively connected to the cutting mechanism, machine feeding and guiding mechanism including a plurality of flexible feeding portions each having a free extremity connectible to a fixed point during feeding of the machine, and means driven by said motor for winding in either of said portions at a plurality of speeds including a plurality of friction clutches selectively operative to control the direction of the feed, means for selectively including the same in different feeds, and supplemental clutch mechanism cooperating with either friction clutch and operative to change the rate of feed.
127. In a room and pillar mining machine having projecting cutting mechanism and slideable on a mine bottom, a driving motor operatively connected to the cutting mechanism, feeding mechanism including a plurality of flexible feeding portions each having a free extremity, either of said portions being disposable to extend from one end of the machine to a fixed point while the other extends from the opposite end to a second fixed point, and means driven by said motor for winding in either of said portions including fast and slow feed mechanism including clutch mechanism operable to change the direction and rate of feed, and friction clutch mechanism including a plurality of friction clutches selectively includable in either the fast or slow feed mechanism and operative to reverse the direction of feed.
128. In a room and pillar mining machine having projecting cutting mechanism and slideable on a mine bottom, a driving motor operatively connected to the cutting mechanism, feeding mechanism including a plurality of flexible feeding portions each having a free extremity, either of said portions being disposable to extend from one end of the machine to a fixed point while the other extends from the opposite end to a second fixed point, and means driven by said motor for winding in either of said portions including fast and slow feed mechanism including clutch mechanism operable to change the direction and rate of feed, and friction clutch mechanism including a plurality of friction clutches selectively includable in either the fast or slow feed mechanism and operative to reverse the direction of feed, and common loading means for said friction clutches.
129. In a room and pillar mining machine, the combination including a frame provided with cutting mechanism including a rigidly projecting cutter bar, driving means for said cutting mechanism, and reversible feeding mechanism for feeding said cutter bar longitudinally into and in either direction across a mine face including a plurality of flexible feeding portions disposable in either direction from either end of said frame and a reversible feed driving member, a plurality of friction clutches concentric therewith and respectively operative on actuation to effect driving thereof in opposite directions, a plurality of sets of gearing operative to drive said member in opposite directions, and means for selectively connecting either of said clutches in either of said gear trains including a controlling member having a movable portion between said clutches.
130. The combination with a mining machine having projecting cutting mechanism and slideable on a mine bottom, of flexible feeding mechanism including a plurality of

- flexible feeding portions each having a free and operative connections whereby different extremity, a driving motor therefor operatively connected to said cutting mechanism, and operative connections whereby said different portions may be drawn in at a predetermined slow or cutting speed while said cutting mechanism rotates in the same direction or at a faster speed including a slow feed gear train and a fast feed gear train, and means including a plurality of friction clutches for connecting either train to draw in different portions. 75
131. The combination with a mining machine having projecting cutting mechanism and slideable on a mine bottom, of flexible feeding mechanism including a plurality of flexible feeding portions each having a free extremity, a driving motor therefor operatively connected to said cutting mechanism, and operative connections whereby different portions may be drawn in at equal predetermined slow or cutting speeds or at equal predetermined faster speeds while said motor rotates in the same direction including a plurality of manually controllable friction devices. 80
132. The combination with a mining machine having projecting cutting mechanism and slideable on a mine bottom, of flexible feeding mechanism including a plurality of flexible feeding portions each having a free extremity, a driving motor therefor operatively connected to said cutting mechanism, and operative connections whereby different portions may be drawn in at a predetermined slow or cutting speed or at a predetermined faster speed while said motor rotates in the same direction including a slow speed gear train and a faster speed gear train and a plurality of frictional devices selectively operative to connect said trains to draw in different portions. 90
133. The combination with a mining machine having projecting cutting mechanism and slideable on a mine bottom, of flexible feeding mechanism including a plurality of flexible feeding portions each having a free extremity, a driving motor therefor operatively connected to said cutting mechanism, and operative connections whereby different portions may be drawn in at a predetermined slow or cutting speed or at a predetermined faster speed while said motor rotates in the same direction including a slow feed gear train and a faster speed gear train, and means including a plurality of friction clutches for connecting said trains to draw in different portions. 105
134. The combination with a mining machine having projecting cutting mechanism and slideable on a mine bottom, of flexible feeding mechanism including a plurality of flexible feeding portions each having a free extremity, a driving motor therefor operatively connected to said cutting mechanism, 110
135. A mining machine slideable on a mine bottom comprising a frame, cutting mechanism thereon including a projecting cutter bar disposed longitudinally of said frame and rigidly connected thereto throughout the cutting operations, and a circulating cutter chain on said bar, flexible feeding means and guiding means for said feeding means about which said flexible feeding means may be directed to enable a lateral cut in a face in either direction providing advance and receding portions during lateral cutting in one direction extending laterally in opposite directions from the opposite ends of said frame and having provision whereby said portions may be reversely disposed respectively as receding and advancing portions 120
136. A mining machine slideable on a mine bottom comprising a frame, cutting mechanism thereon including a projecting cutter bar disposed longitudinally of said frame and rigidly connected thereto throughout the cutting operations, and a circulating cutter chain on said bar, flexible feeding means, guiding means for said feeding means about which said flexible feeding means may be directed, to enable a lateral cut in a face in either direction, to provide advance and receding portions during lateral cutting in one direction extending laterally in opposite directions from the opposite ends of said frame and having provision whereby said portions may be reversely disposed respectively as receding and advancing portions 125

during lateral cutting in the opposite direction, a motor operatively connected with said cutter chain, driving connections between said motor and said flexible feeding means 5 including a feed operating member operatively engaging said flexible feeding means, and driving connections between the motor and said feed operating member operative to effect operation of said member by said 10 motor at a plurality of speeds and in opposite directions at each of said speeds including speed changing gearing including a plurality of clutches between said motor and said feed operating member and operative 15 when engaged both to change the speed and the direction of rotation of the feed operating member and a plurality of friction clutches selectively operable to reverse the direction of feed and arranged between 20 said first mentioned clutches and one of said elements between which said first mentioned clutches are disposed.

137. A mining machine slidable on a mine bottom comprising a machine frame, flexible feeding means including a plurality of flexible feeding portions each having a free extremity, and feed operating means operative to draw in either portion at either of a plurality of different predetermined 30 speeds including a friction device through which power is transmitted to draw in each portion at the lower speed and another friction device through which power is transmitted to draw in each portion at the 35 higher speed.

138. A mining machine slidable on a mine bottom comprising a machine frame, flexible feeding means including a plurality of flexible feeding portions each having a free 40 extremity, and feed operating means operative to draw in either portion at either of a plurality of different predetermined speeds including a friction device through which power is transmitted to draw in each 45 portion at the lower speed and another friction device through which power is transmitted to draw in each portion at the higher speed, and a single controlling means controlling either friction device.

139. In a mining machine, the combination comprising a machine frame, cutting mechanism thereon, feed operating means thereon, fast and slow speed driving mechanism for said feed operating means including a shaft rotatable on a horizontal transverse axis and at different predetermined speeds, friction means controlling the rotation of said shaft at each of said speeds, and jaw clutch means between said shaft 50 and said feed operating means.

140. In a mining machine, the combination comprising a machine frame, cutting mechanism thereon, feed operating means thereon, fast and slow speed driving mechanism for 60 said feed operating means including a

shaft rotatable on a horizontal transverse axis and at different predetermined speeds, friction means controlling the rotation of said shaft at each of said speeds, and clutch means between said shaft and said feed operating means coaxial with and reciprocable longitudinally of said shaft.

141. In a mining machine, the combination comprising a machine frame, cutting mechanism thereon, feed operating means thereon, a motor, fast and slow speed driving mechanism for said feed operating means including a shaft rotatable on a horizontal transverse axis and at different predetermined speeds, driving means for said shaft including a horizontal shaft disposed in a plane to which said first mentioned shaft is perpendicular and driving connections between said shafts, friction means controlling the rotation of said shaft at each of said speeds, and clutch means between said shaft and said feed operating means coaxial with and reciprocable longitudinally of said shaft.

142. In a mining machine, the combination comprising a machine frame, cutting mechanism thereon, feed operating means thereon, a motor, fast and slow speed driving mechanism for said feed operating means including a shaft rotatable on a horizontal transverse axis and at different predetermined speeds, driving means for said shaft including a horizontal shaft disposed in a plane to which said first mentioned shaft is perpendicular and driving connections between said shafts, friction clutch means controlling the rotation of said first mentioned shaft at each of said speeds, and clutch means between said shaft and said feed operating means coaxial with and reciprocable longitudinally of said shaft.

143. In a mining machine, the combination comprising a machine frame, cutting mechanism thereon, feed operating means thereon, and frictionally controlled fast and slow speed driving mechanism therefor including a longitudinally disposed horizontal shaft rotatable at a plurality of predetermined speeds, a transversely disposed horizontal shaft, driving connections between said shafts said last mentioned shaft being driven by said first mentioned shaft and its rotation at each of said predetermined speeds being friction controlled, and clutch means for selectively connecting and disconnecting said feed operating means and said second mentioned horizontal shaft.

144. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, said portions constituting during cutting across a face ad-

vancing and receding portions, a motor having a rotating member, a horizontal shaft rotating on rotation of said rotating member, a vertical shaft, a bevel gear on said vertical shaft, a bevel pinion on said horizontal shaft meshing with the gear on said vertical shaft, a horizontal transverse shaft to the rear of said vertical shaft, meshing driving and driven members coaxial with said horizontal shafts respectively and cooperating in effecting driving of said second mentioned horizontal shaft, and means rotatable by said second mentioned horizontal shaft to wind in either of said opposite feeding portions.

145. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, said portions constituting during cutting across a face advancing and receding portions, a motor having a rotating member, a horizontal shaft rotating on rotation of said rotating member, a vertical shaft, a bevel gear on said vertical shaft, a bevel pinion on said horizontal shaft meshing with the gear on said vertical shaft, a horizontal transverse shaft to the rear of said vertical shaft, meshing driving and driven members coaxial with said horizontal shafts respectively and cooperating in effecting driving of said second mentioned shaft, and means rotatable by said second mentioned horizontal shaft to wind in either of said opposite feeding portions.

146. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, said portions constituting during cutting across a face advancing and receding portions, a motor having a rotating member, a horizontal shaft rotating on rotation of said rotating member, a vertical shaft, a bevel gear on said vertical shaft, a bevel pinion on said horizontal shaft meshing with the gear on said vertical shaft, a horizontal transverse shaft to the rear of said vertical shaft, meshing driving and driven members coaxial with said horizontal shafts respectively and cooperating in effecting driving of said second mentioned shaft, means rotatable by said second mentioned horizontal shaft to wind in either of said opposite feeding portions, and clutch means between said shaft and said means.

147. A mining machine slidable on a mine bottom comprising cutting mechanism including a projecting cutter bar and flexible

feeding mechanism including a plurality of flexible feeding portions adapted to act on the opposite ends of the machine frame and having free extremities adapted for connection to fixed points, a motor operatively connected to said cutting mechanism, and means driven by said motor and including elements selectively connectible thereto for drawing in either portion automatically at the same predetermined cutting speed and at a predetermined higher speed, said means and said included elements including a member rotatable on a horizontal axis extending transversely of the machine at the opposite end of the motor from the cutter bar, and clutch mechanism coaxial with said shaft.

148. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and including elements selectively connectible thereto for drawing in either portion automatically at the same predetermined cutting speed and at a predetermined higher speed, said means and said included elements including a member rotatable on a horizontal axis extending transversely of the machine at the opposite end of the motor from the cutter bar, clutch mechanism coaxial with said shaft.

149. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and including elements selectively connectible thereto for drawing in either portion automatically at the same predetermined cutting speed and at a predetermined higher speed, said means and said included elements including a member rotatable on a horizontal axis extending transversely of the machine at the opposite end of the motor from the cutter bar, and clutch mechanism coaxial with said shaft.

150. A mining machine slidable on a mine bottom comprising cutting mechanism including a projecting cutter bar and flexible feeding mechanism including a plurality of flexible feeding portions adapted to act on the opposite ends of the machine frame and

- having free extremities adapted for connection to fixed points, a motor operatively connected to said cutting mechanism, and means driven by said motor and including 5 elements selectively connectible thereto for drawing in either portion automatically at a predetermined cutting speed and at the same predetermined higher speed, said means and said included elements including 10 a member rotatable on a horizontal axis extending transversely of the machine at the opposite end of the motor from the cutter bar, clutch mechanism coaxial with said axis, and driving means for said member 15 including a worm rotating on an axis disposed in a plane to which said horizontal axis is perpendicular.
151. A mining machine slideable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and including elements selectively connectible thereto for drawing in either portion automatically at 20 the same predetermined cutting speed and at the same predetermined higher speed, said means and said included elements including a member rotatable on a horizontal axis extending transversely of the machine at the opposite end of the motor from the cutter bar, and clutch mechanism coaxial with said axis.
152. A mining machine slideable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and including elements selectively connectible thereto for drawing in either portion automatically at 25 the same predetermined cutting speed and at the same predetermined higher speed, said means and said included elements including a member rotatable on a horizontal axis extending transversely of the machine at the opposite end of the motor from the cutter bar, and clutch mechanism coaxial with said axis.
153. A mining machine slideable on a mine bottom comprising cutting mechanism including a projecting cutter bar and feeding mechanism including a plurality of flexible feeding portions adapted to act on the opposite ends of the machine frame and having free extremities adapted for connection to fixed points, said portions constituting during cutting across a face advancing and receding portions, a motor operatively connected to 70 said cutting mechanism, and means driven by said motor and cooperating with said flexible feeding portions to effect movement of said machine and operative to draw in the receding portion at a plurality of predetermined speeds, said last mentioned means including a transversely extending horizontal shaft, friction controlled means for rotating the same at a plurality of predetermined speeds, and means driven by said shaft and operative on rotation in one direction to wind in said receding portion.
154. A mining machine slideable on a mine bottom comprising cutting mechanism including a projecting cutter bar and feeding mechanism including a plurality of flexible feeding portions adapted to act on the opposite sides of the frame and having free extremities adapted for connection to fixed points, a motor operatively connected to 75 said cutting mechanism, and means driven by said motor and including elements selectively connectible thereto for drawing in either portion automatically at the same predetermined cutting speed and at the same predetermined higher speed, said means and its included elements including a shaft rotatable on a horizontal transverse axis disposed at the opposite end of the motor from the cutter bar, friction controlled plural-speed driving mechanism for said shaft, and clutch mechanism coaxial with said shaft and shiftable oppositely longitudinally thereof and controlling the winding in of each of said portions.
155. A mining machine slideable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and cooperating with said flexible feeding mechanism to effect movement of said machine including means for winding in that flexible feeding portion which extends rearwardly from said machine during a cut across a face automatically at a plurality of different predetermined speeds including a winding member, a horizontal transversely disposed shaft, friction controlled means for rotating said shaft at a plurality of different speeds proportional to said speeds of drawing in, the rotation of said shaft being friction controlled at each speed, and clutch means controlling the driving of said winding member by said shaft.

156. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor for drawing in either portion automatically at a predetermined cutting speed and at a predetermined higher speed, said means including a shaft rotatable on a horizontal axis, friction controlled multi-speed driving gearing therefor operative to drive the same at a plurality of predetermined speeds including gear elements coaxial with said shaft and a plurality of clutches also coaxial therewith, the rotation of said shaft being frictionally controlled at each of said plurality of speeds, and selectively operable clutches beyond said multi-speed gearing operative respectively to effect drawing in of different portions.

157. In a mining machine slidable on a mine bottom and having projecting cutting mechanism, a flexible feeding member, a feed operating member operatively connected thereto, a motor, and means driven thereby for rotating said feed operating member at different speeds in opposite directions without reversal of said motor including a shaft, a pair of driven members coaxial with said shaft, driving means for said members effecting rotation thereof at different angular speeds, and friction means including a plurality of frictional devices selectively operable to cause either of said members to drive said shaft.

158. In a mining machine slidable on a mine bottom and having projecting cutting mechanism, a flexible feeding member, a feed operating member operatively connected thereto, and means for rotating said feed operating member at different speeds in opposite directions including a motor, a shaft, a pair of driven members coaxial with said shaft, motor driven driving means for said members effecting rotation thereof in opposite directions and at different angular speeds, and frictional means including a plurality of frictional devices selectively operable to cause either of said members to drive said shaft.

159. In a mining mechanism, a mining machine slidable upon a mine bottom and having projecting cutting mechanism, a flexible feeding member and means operatively engaging said flexible feeding member for moving said machine relative to one extremity thereof and including a shaft, means including a friction clutch for connecting said feed operating member to said shaft, and means for rotating said shaft in

different directions and at different angular speeds while said motor is rotating in one direction including a plurality of driven members coaxial with said shaft, and friction means including a plurality of frictional devices selectively operable to cause either of said members to drive said shaft.

160. In a mining mechanism, a mining machine slidable on a mine bottom and having projecting cutting mechanism, a flexible feeding member and means operatively engaging said flexible feeding member for moving said machine relative to the extremities thereof and including a shaft, means including a friction clutch for connecting said feed operating member to said shaft, a motor, and means for rotating said shaft in different directions and at different angular speeds while said motor is rotating in one direction including a plurality of driving members constantly driven by said motor and a plurality of driven members coaxial with said shaft, and friction means including a plurality of frictional devices selectively operable to cause either of said members to drive said shaft.

161. In a mining machine slidable on a mine bottom and having projecting cutting mechanism, a flexible feeding member, a feed operating member operatively connected thereto, a motor, and means driven thereby for rotating said feed operating member at different speeds in opposite directions without reversal of said motor including a shaft, a pair of driven members coaxial with said shaft, driving means for said members effecting rotation thereof at different angular speeds, and separate friction clutch mechanisms for respectively connecting said members to said shaft.

162. In a mining machine slidable on a mine bottom and having projecting cutting mechanism, a flexible feeding member, a feed operating member operatively connected thereto, and means for rotating said feed operating member at different speeds in opposite directions including a motor, a shaft, a pair of driven members coaxial with said shaft, motor driven driving means for said members effecting rotation thereof in opposite directions and at different angular speeds, and separate friction clutch mechanisms for respectively connecting said members to said shaft.

163. In a mining mechanism, a mining machine slidable upon a mine bottom and having projecting cutting mechanism, a flexible feeding member and means operatively engaging said flexible feeding member for moving said machine relative to one extremity thereof and including a shaft, means including a friction clutch for connecting said feed operating member to said shaft, and means for rotating said shaft in different directions and at different angular

speeds while said motor is rotating in one direction including a plurality of driven members coaxial with said shaft, and friction clutch means for operatively connecting 5 said members to said shaft.

164. In a mining mechanism, a mining machine slideable on a mine bottom and having projecting cutting mechanism, a flexible feeding member and means operatively 10 gaging said flexible feeding member for moving said machine relative to the extremities thereof and including a shaft, means including a friction clutch for connecting said feed operating member to said shaft, a 15 motor, and means for rotating said shaft in different directions and at different angular speeds while said motor is rotating in one direction including a plurality of driving members constantly driven by said 20 motor and a plurality of driven members coaxial with said shaft, and friction clutch means for operatively connecting said members to said shaft.

165. In a room and pillar mining machine having fixedly projecting cutting mechanism and slideable directly on a mine bottom, a driving motor operatively connected to the cutting mechanism, machine feeding and guiding mechanism including a 25 plurality of flexible feeding portions each having a free extremity and extending laterally from opposite ends of said machine, one of said portions constituting an advancing portion and the other a receding portion 30 during cutting across a face, and means driven by said motor for winding in that portion which constitutes the receding portion at a plurality of predetermined speeds, said means being friction controlled at each 35 speed and comprising a pair of coaxial members, friction mechanisms cooperating with each of said members, and manual controlling means therefor operable only to effect 40 alternative operation of said friction mechanisms, operation of said different friction mechanisms causing a change in winding speed.

166. In combination, in a mining machine, a frame provided with a rigidly projecting 45 cutter bar having a circulating cutter chain, a motor on said frame for actuating said chain, and feeding mechanism operative to sump said bar into a working face including a flexible portion extending from a 50 point adjacent the rear end of said frame to a point nearer the face than said end, means for winding in said portion permitting winding in thereof at a plurality of predetermined speeds while said motor rotates in one 55 direction including a plurality of selectively operable friction mechanisms, and actuating means therefor permitting only alternative operation thereof.

167. The combination in a mining machine, 60 of feeding mechanism therefor including

plurality of flexible feeding portions adapted to act on the opposite ends of the machine frame and having free extremities adapted for connection to fixed points, and means for winding in each of said portions at a 70 plurality of predetermined speeds including a friction clutch in each feed, and controlling means for said clutches including a controlling member, said controlling member and said clutches being disposed coaxially 75 and said member being reversely movable to actuate different clutches.

168. The combination in a mining machine, of feeding mechanism therefor including a plurality of flexible feeding portions 80 adapted to act on the opposite ends of the machine frame and having free extremities adapted for connection to fixed points, and means for winding in each of said portions at a plurality of predetermined speeds including 85 a plurality of friction clutches selectively operable to reverse the direction of feed, and feed controlling mechanism including mechanism for selectively actuating said different clutches to effect feed in opposite directions. 90

169. The combination with a mining machine having projecting cutting mechanism and slideable on a mine bottom, of flexible feeding and machine guiding mechanism including a plurality of flexible feeding portions each having a free extremity, a driving motor therefor operatively connected to said cutting mechanism, and operative connections whereby different portions may be drawn in at a predetermined slow or cutting speed while said cutting mechanism rotates in the same direction including a plurality of manually controllable friction devices two of which are included in each 95 feed. 100

170. The combination with a mining machine having projecting cutting mechanism which comprises a cutter chain carrying cutter bar disposed longitudinally of said machine throughout cutting and slideable on a 110 mine bottom, of flexible feeding and machine guiding mechanism including a plurality of flexible feeding portions each having a free extremity, a driving motor therefor operatively connected to said cutting mechanism, and operative connections whereby different portions may be drawn in at the same predetermined slow or cutting speed while said cutting mechanism rotates in the same direction including a plurality of clutches each 115 comprising coaxial mutually engageable elements and whereby one of said portions may be drawn in at a predetermined higher speed. 120

171. The combination with a mining machine having projecting cutting mechanism which comprises a cutter chain carrying cutter bar disposed longitudinally of said machine throughout cutting and slideable on a mine bottom, of flexible feeding and ma- 125

- chine guiding mechanism including a plurality of flexible feeding portions each having a free extremity, a driving motor therefor operatively connected to said cutting mechanism, and operative connections whereby different portions may be drawn in at a predetermined slow or cutting speed while said cutting mechanism rotates in the same direction including a plurality of clutches each 10 comprising coaxial mutually engageable elements and controlling mechanism inhibiting simultaneous operation of said clutches, and whereby one of said portions may be drawn in at a predetermined higher speed.
- 15 172. The combination with a mining machine having projecting cutting mechanism and slideable on a mine bottom, of flexible feeding and machine guiding mechanism including a plurality of flexible feeding portions each having a free extremity, a driving motor therefor operatively connected to said cutting mechanism, and operative connections whereby different portions may be drawn in at a predetermined slow or cutting 20 speed while said cutting mechanism rotates in the same direction including a slow speed gear train and a plurality of frictional devices selectively operative to connect said train to draw in different portions, and a 25 truck driving element driven by said operative connections.
173. The combination with a mining machine having projecting cutting mechanism and slideable on a mine bottom, of flexible feeding mechanism including a plurality of flexible feeding portions each having a free extremity, a driving motor therefor operatively connected to said cutting mechanism, and operative connections whereby different 30 portions may be drawn in at a predetermined slow or cutting speed while said cutting mechanism rotates in the same direction including a slow feed gear train, means including a plurality of friction clutches for 35 connecting said train to draw in different portions, and a truck driving element driven by said operative connections.
174. The combination with a mining machine having projecting cutting mechanism 40 which comprises a cutter chain carrying cutter bar disposed longitudinally of said machine throughout cutting, and slideable on a mine bottom, of flexible feeding mechanism including a plurality of flexible feeding 45 portions each having a free extremity, a driving motor therefor operatively connected to said cutting mechanism, and operative connections whereby different portions may be drawn in at a predetermined slow or 50 cutting speed or at a higher predetermined speed while said cutting mechanism rotates in the same direction including a slow speed gear train and a fast feed gear train, frictional controlling means for said gear trains, 55 and means including a plurality of clutches

each including coaxial mutually engageable elements for connecting either train to draw in different portions.

175. The combination with a mining machine having projecting cutting mechanism and slideable on a mine bottom, of feeding mechanism including flexible feeding means including a plurality of flexible feeding portions each having a free extremity, a driving motor operatively connected to said cutting mechanism, and operative connections whereby different portions may be drawn in at a predetermined fast or moving speed while said motor rotates in the same direction including a plurality of manually controllable friction devices of which two are operative during the drawing in of each portion.

176. A mining machine slideable on a mine bottom comprising a machine frame, cutting mechanism flexible feeding means including advance and receding portions adapted to extend during cutting across a face in opposite directions from opposite ends of said frame, winding means for winding in either of the same at a cutting speed, a truck driving member, and actuating means for said means and said member including a shaft coaxial with said member for rotating the same and a worm coaxial with said shaft for driving said winding means.

177. A mining machine slideable on a mine bottom comprising a machine frame, cutting mechanism, flexible feeding means including advance and receding portions adapted to extend during cutting across a face in opposite directions from opposite ends of said frame, winding means for winding in either of the same at a cutting speed and at a higher speed, a truck driving member, and actuating means for said member including a shaft coaxial with said member for rotating the same and a worm coaxial with said shaft for driving said winding means.

178. A mining machine slideable on a mine bottom comprising a machine frame, cutting mechanism, flexible feeding means including advance and receding portions adapted to extend during cutting across a face in opposite directions from opposite ends of said frame whereby the same constitute advancing and receding portions, winding means for winding in said receding portion at a cutting speed, a truck driving member and actuating means for said means and said member including a shaft coaxial with said member for rotating the same and a worm coaxial with said shaft for driving said winding means.

179. In a mining machine, the combination comprising a machine frame, cutting mechanism thereon, feed operating means thereon, fast and slow speed driving mechanism for said feed operating means including a shaft rotatable on a horizontal transverse

axis and at different predetermined speeds, driving means for said shaft including a horizontal shaft disposed in a plane to which said first mentioned shaft is perpendicular and driving connections between said shafts, friction means controlling the rotation of said first mentioned shaft at each of said speeds, and clutch means between said shaft and said feed operating means coaxial with and reciprocable longitudinally of said shaft, and truck driving means coaxial with one of said shafts.

180. In a mining machine, the combination comprising a machine frame, cutting mechanism thereon, feed operating means thereon, fast and slow speed driving mechanism for said feed operating means including a shaft rotatable on a horizontal transverse axis and at different predetermined speeds, driving means for said shaft including a horizontal shaft disposed in a plane to which said first mentioned shaft is perpendicular and driving connections between said shafts, friction means controlling the rotation of said first mentioned shaft at each of said speeds, and clutch means between said shaft and said feed operating means coaxial with and reciprocable longitudinally of said shaft, and truck driving means driven by one of said shafts.

181. The combination of a mining machine having projecting cutting mechanism and slidable on a mine bottom, of flexible feeding and machine guiding mechanism including a plurality of flexible feeding portions each having a free extremity, a driving motor therefor operatively connected to said cutting mechanism, winding means, and operative connections between the same and said motor whereby different portions may be drawn in at a predetermined slow or cutting speed and at a predetermined higher speed including a plural-speed gear train, clutch means for changing the speed transmitted, frictional means controlling the drawing in at all speeds, and a truck driving element operatively connected to said motor and rotating on a horizontal axis.

182. The combination of a mining machine having projecting cutting mechanism and slidable on a mine bottom, of flexible feeding and guiding mechanism including a plurality of flexible portions each having a free extremity adapted for connection to a desired point, a driving motor, winding means driven by said motor and operative to wind in either of said portions at either of two different predetermined speeds, and a motor driven truck driving element rotatable on a horizontal axis.

183. The combination of a mining machine having projecting cutting mechanism and slidable on a mine bottom, of flexible feeding and guiding mechanism including a plurality of flexible portions each

having a free extremity and one adapted to constitute an advance portion and the other a receding portion during cutting across a face, winding means driven by said motor for winding in the first mentioned portion at a cutting speed and the second mentioned portion at a plurality of different predetermined speeds, and a motor driven truck driving element rotatable on a horizontal axis.

184. The combination with a mining machine having projecting cutting mechanism and slidable on a mine bottom, of flexible feeding mechanism including a plurality of flexible feeding portions each having a free extremity, a driving motor therefor operatively connected to said cutting mechanism, and operative connections whereby different portions may be drawn in at a predetermined fast or moving speed while said motor rotates in the same direction including a plurality of coaxial clutches, and a truck driving member rotatable upon a horizontal axis.

185. The combination with a mining machine adapted to be carried about a mine upon a truck and having projecting cutting mechanism and slidable on the mine bottom during cutting, a flexible feeding mechanism including a plurality of flexible feeding portions each having a free extremity, a driving motor therefor operatively connected to said cutting mechanism, and operative connections whereby different portions may be automatically drawn in at the same predetermined speed while the motor rotates in the same direction including a plurality of friction clutches and controlling mechanism inhibiting simultaneous operation of said clutches, and means for driving a truck rotating on a horizontal axis in alignment with the axes of said clutches.

186. The combination with a mining machine having projecting cutting mechanism and slidable on a mine bottom, of flexible feeding mechanism including a plurality of flexible feeding portions each having a free extremity, a driving motor therefor operatively connected to said cutting mechanism, and operative connections whereby different portions may be drawn in at equal predetermined fast speeds while said motor rotates in the same direction including a gear train and a plurality of devices selectively operative to connect said train to draw in different portions, said gear train including a plurality of elements all of which rotate on horizontal axes, and a truck driving element coaxial with one of said shafts.

187. The combination with a mining machine having projecting cutting mechanism and slidable on a mine bottom, of flexible feeding mechanism including a plurality of flexible feeding portions each having a free extremity, a driving motor therefor oper-

- atively connected to said cutting mechanism, and operative connections whereby different portions may be drawn in at the same predetermined slow speed while said cutting mechanism rotates in the same direction including a gear train, and means including a plurality of clutches for connecting said gear train to draw in different portions, said gear train including a plurality of horizontal shafts and intermeshing elements coaxial therewith, and truck driving means including a driving member coaxial with one of said shafts.
188. In a mining machine, feeding mechanism including a feed operating member, a motor, and driving connections between the same operative to effect operation of said member by said motor at a plurality of speeds and in opposite directions including multi-speed driving gearing including a plurality of clutches and a plurality of friction clutches between said first mentioned clutches and one of said first mentioned elements, said driving connections also being operative to effect driving of a truck upon which the machine is disposed during running about a mine.
189. In a mining machine feeding mechanism, a feed operating member, a motor, and driving connections between the same operative to effect operation of said member by said motor at a plurality of speeds and in opposite directions including speed changing gearing including a plurality of clutches and a plurality of friction clutches selectively operative to reverse the direction of feed and arranged between said first mentioned clutches and one of said first mentioned elements, said driving connections also being operative to effect driving of a truck upon which the machine is disposed during running about a mine.
190. The combination of a mining machine having projecting cutting mechanism and slidain on a mine bottom, of flexible machine feeding and guiding mechanism including a plurality of flexible portions each having a free extremity adapted for connection to a desired point, a driving motor, winding means driven by said motor and operative to wind in either of said portions at a plurality of predetermined speeds without reversal of said motor, and a motor driven truck driving element rotatable on a horizontal axis.
191. The combination with a mining machine having projecting cutting mechanism and slidain on a mine bottom, of flexible feeding and machine guiding mechanism including a plurality of flexible feeding portions each having a free extremity, a driving motor therefor operatively connected to said cutting mechanism, and operative connections whereby different portions may be drawn in at predetermined speeds while the cutting mechanism rotates in the same direction, the connections operative during the drawing in of either portion including a pair of friction devices each of which may be unloaded at starting.
192. The combination, in a mining machine having projecting cutting mechanism and slidable on a mine bottom, of flexible feeding and machine guiding mechanism including a plurality of flexible feeding portions each having a free extremity and adapted to extend from diagonally opposite positions during cutting across a mine face, a motor comprising elements the reaction between which causes rotation of one of said elements, a truck driving member, and power transmission mechanism operative to drive said truck driving member and effect the drawing in at predetermined speeds of the different flexible feeding portions including friction mechanism through which said rotating motor element transmits power to the feeding mechanism and the truck driving mechanism permitting the motor to start disconnected from both.
193. The combination with a mining machine slidable on its bottom directly on a mine bottom, of a feed operating member adjacent the rear end of said machine and operable to effect sumping, means including a plurality of mechanisms for selectively driving said feeding operating member in opposite directions, each of said mechanisms including friction controlling mechanism individual thereto and independent operating means therefor.
194. The combination with a mining machine slidable on its bottom directly on a mine bottom, of a feed operating member adjacent the rear end of said machine and operable to effect sumping, means including a plurality of mechanisms for selectively driving the same in different directions and at different speeds, each of said mechanisms including friction controlling mechanism individual thereto and independent operating means therefor.
195. The combination with a mining machine, of a feed operating member, and means for driving the same in opposite directions including a plurality of mechanical reversing mechanisms each including frictional controlling means and operating mechanism therefor.
196. In a mining machine, a machine frame slidable upon a mine bottom during cutting, cutting mechanism projecting therefrom, a rotatable feeding member on said frame, and a driving mechanism therefor on said frame including a friction controlled speed changing mechanism operative to provide a plural predetermined speed drive frictionally controlled at each speed and a friction controlled reversing mechanism.
197. In a mining machine, a frame, cut-

ting mechanism projecting therefrom, a rotatable feeding member on said frame, a driving mechanism for said member including a friction controlled speed changing mechanism operative to effect drive at different predetermined speeds under friction control and a friction controlled reversing mechanism, and independent controlling members for each of said friction controlled mechanisms.

198. In a mining machine, a frame slideable upon a mine bottom during cutting, cutting mechanism projecting therefrom, a rotatable feeding member on said frame adapted to cooperate with flexible feeding means, plural predetermined speed reversing driving mechanism therefor including a plurality of friction clutches, and a plurality of independent controlling members for said clutches.

199. In a mining machine, a frame, cutting mechanism projecting therefrom, a feeding member on said frame, a shaft, operative connections between said member and said shaft, and reversible plural predetermined speed driving mechanism for said shaft including a plurality of friction clutches certain of which control the direction and others the speed of said shaft.

200. In a mining machine, a frame, cutting mechanism projecting therefrom, a feeding member on said frame, a motor a shaft, operative connections between said member and said shaft including a clutch, and reversing and plural predetermined speed driving mechanisms for said shaft including a plurality of friction clutches.

201. In a mining machine, a machine frame, a rotatable feeding member thereon, a transverse shaft, operative connections between the same, a longitudinally disposed shaft, friction mechanism for rotating said longitudinally disposed shaft at a plurality of speeds, and friction mechanism for rotating said transverse shaft from said longitudinal shaft in either direction.

202. In a mining machine, the combination comprising a machine frame, cutting mechanism thereon, feed operating means thereon, fast and slow speed driving mechanisms for said feed operating means, and a separate controlling friction included in each mechanism, said feed operating means including a feed operating member rotatable on a vertical axis.

203. In a mining machine, the combination comprising a machine frame, cutting mechanism thereon, a feed operating member thereon, and mechanisms for driving said feed operating member in either direction and at different predetermined speeds including a separate controlling friction for each mechanism.

204. In a mining machine, the combination comprising a machine frame, cutting

mechanism thereon, a feed operating member thereon, and mechanisms for driving said feed operating member in either direction at different predetermined speeds including a controlling friction clutch for each mechanism so disposed as to be driven at speeds directly proportional to said different speeds.

205. In a mining machine, the combination comprising a machine frame, cutting mechanism thereon, a feed operating member thereon, predetermined fast and slow speed driving mechanisms for said feed operating member including a controlling friction individual to each mechanism, and mechanical means for reversing the direction of feed at will.

206. In a mining machine, the combination comprising a machine frame, cutting mechanism thereon, a feed operating member thereon, fast and slow speed driving mechanisms for said feed operating member including a separate controlling friction individual to each mechanism, and means for reversing the direction of feed at will whereby said machine may cut in opposite directions.

207. In a mining machine, the combination comprising a machine frame, cutting mechanism thereon, a feed operating member thereon, mechanisms for driving said feed operating member in opposite directions at different predetermined speeds including a controlling friction individual to each mechanism, and mechanical means for reversing the direction of feed at will.

208. In a mining machine, the combination comprising a machine frame, cutting mechanism thereon, a feed operating member thereon, mechanisms for driving said feed operating member in opposite directions at different predetermined speeds including a separate controlling friction individual to each mechanism, and means for reversing the direction of feed at will whereby said machine may cut in opposite directions.

209. In a mining machine, flexible feeding means including advance and receding flexible feeding portions, feed operating means cooperating with said flexible feeding means, a transverse feed operating shaft, a plurality of driving members, a plurality of cooperating driving members driven thereby and disposed concentrically with said shaft, and means including friction clutch mechanism for selectively connecting said last mentioned members and shaft.

210. In a mining machine, flexible feeding means including advance and receding flexible feeding portions, feed operating means cooperating with said flexible feeding means, a feed operating shaft, a plurality of driving elements therefor spaced apart thereon, a plurality of means for connecting

said driving elements thereto including friction clutches each controlling the connection of one of said means to said shaft, and a single means for selectively operating said connecting means including a controlling member disposed parallel to said shaft, and supplemental friction clutch mechanism.

211. In a mining machine, a feed operating shaft, a plurality of drive members concentric therewith and spaced apart thereon, a sleeve on said shaft, means for connecting said sleeve to said shaft, means for selectively connecting said driving members to said sleeve, and a truck driving member driven by said shaft.

212. In a mining machine adapted to cut according to the room and pillar method and to slide upon its bottom over a mine bottom during cutting, cutting mechanism including a cutter bar having a circulating cutter chain, a vertically disposed shaft carrying a bevel gear constituting an actuating element for said cutting mechanism, a transversely extending shaft, a motor, a motor rotated shaft having a bevel pinion meshing with said bevel gear and a driving member intermediate said motor and said bevel gear constituting a driving element for said transverse shaft, a feed operating member adapted to be rotated by said transverse shaft, and flexible feeding means with which said member cooperates in feeding said machine into a face and thereafter moving it transversely of such face during cutting.

213. In a mining machine adapted to cut according to the room and pillar method and to slide upon its bottom over a mine bottom during cutting, cutting mechanism including a cutter bar having a circulating cutter chain, a vertically disposed shaft carrying a bevel gear constituting an actuating element for said cutting mechanism, a transversely extending shaft disposed at a point more remote from the front of said cutter bar than said vertically disposed shaft, a motor, a motor rotated shaft having a bevel pinion meshing with said bevel gear and a driving member intermediate said motor and said bevel gear constituting a driving element for said transverse shaft, a feed operating member adapted to be rotated by said transverse shaft, and flexible feeding means with which said member cooperates in feeding said machine into a face and thereafter moving it transversely of such face during cutting.

214. A mining machine slidable on a mine bottom comprising a machine frame, cutting mechanism, a motor on said machine frame having a longitudinally arranged shaft actuating said cutting mechanism, a guiding member adjacent a rear corner of said machine frame, a flexible feeding portion extending about said guiding member

and having a free end, and means actuated by said motor for winding in said portion at a plurality of friction controlled predetermined speeds including a feed operating member cooperating with said portion, and actuating means therefor including a plurality of operatively connected shafts one parallel to the motor shaft and offset therefrom and one extending transversely of said machine frame and operative connections between the last mentioned shaft and the feed operating member.

215. A mining machine slidable on a mine bottom comprising a machine frame, cutting mechanism, a motor on said machine frame having a shaft lying longitudinally of said frame and actuating said cutting mechanism, a guiding member adjacent a rear corner of said machine frame, a flexible feeding portion extending about said guiding member and having a free end and means actuated by said motor for winding in the same at two friction controlled predetermined speeds including a feed operating member cooperating with said portion, and actuating means therefor including a plurality of operatively connected shafts one parallel to the motor shaft and offset therefrom and one extending transversely of said machine frame and operative connections between the last mentioned shaft and the feed operating member rotating on an axis offset from the axis of both of said first mentioned shafts.

216. A mining machine slidable on a mine bottom comprising a machine frame, cutting mechanism, a motor on said machine frame actuating said cutting mechanism, a guiding member adjacent a rear corner of said machine frame, a flexible feeding portion extending about said guiding member and having a free end and means actuated by said motor for winding in the same at two friction controlled predetermined speeds including a feed operating member cooperating with said portion, and actuating means therefor including a plurality of operatively connected shafts one parallel to the motor shaft and offset therefrom and one extending transversely of said machine frame and operative connections including a manually controllable clutch between the last mentioned shaft and the feed operating member.

217. A mining machine slidable on a mine bottom comprising a machine frame, cutting mechanism, a motor on said machine frame actuating said cutting mechanism, a guiding member arranged adjacent one of the rear corners of said machine frame, a flexible feeding portion extending about said guiding member and having a free end and adapted to constitute during cutting across a face a receding portion, and means for winding in said portion at a plurality of

predetermined speeds including a feed operating member, a transversely extending shaft, means for rotating said shaft at different predetermined speeds friction controlled at each speed, and means for connecting said shaft at will in driving relation to said feed operating member.

218. A mining machine slidable on a mine bottom comprising a machine frame, cutting mechanism, a motor on said machine frame actuating said cutting mechanism, a guiding member arranged adjacent one of the rear corners of said machine frame, a flexible feeding portion extending about said guiding member and having a free end and adapted to constitute during cutting across a face a receding portion, and means for winding in said portion at a plurality of predetermined speeds without reversal of said motor including a feed operating member, a transversely extending shaft, friction controlled means for rotating said shaft at different predetermined speeds, and means for connecting said shaft at will in driving relation to said feed operating member.

219. A mining machine slidable on a mine bottom comprising a machine frame, cutting mechanism, a motor on said machine frame actuating said cutting mechanism, a guiding member arranged adjacent one of the rear corners of said machine frame, a flexible feeding portion extending about said guiding member and having a free end and adapted to constitute when cutting across a face the receding portion, and means for winding in said portion at a plurality of predetermined speeds without reversal of said motor including a feed operating member, a transversely extending shaft, friction controlled means for rotating said shaft at different predetermined speeds, and means for connecting said shaft at will in driving relation to said feed operating member including a positive clutch element reciprocable longitudinally of said shaft.

220. In a mining machine, a machine frame having projecting therefrom cutting mechanism, a motor on said frame having a power shaft extending longitudinally of said frame, and feeding mechanism for moving said machine over a mine bottom including a feed operating member rotatable on a vertical axis, and means for driving the same in opposite directions while said motor runs in one direction including a worm wheel rotatable on a vertical axis and operative on rotation to effect rotation of said feed operating member, a worm engaging said worm wheel and supported for rotation on a horizontal axis, a horizontal shaft supporting and constituting driving means for said worm, and reversing gearing between said shaft and said motor.

221. In a mining machine, a machine frame having projecting therefrom cutting

mechanism, a motor on said frame having a power shaft extending longitudinally of said frame and feeding mechanism for moving said machine over a mine bottom including a feed operating member rotatable on a vertical axis, and means for driving the same in opposite directions and varying the speed thereof while said motor runs in one direction including a worm wheel rotatable on a vertical axis and operative on rotation to effect rotation of said feed operating member, a worm engaging said worm wheel and supported for rotation on a horizontal axis, a horizontal shaft supporting and constituting driving means for said worm, and reversing gearing and friction controlled driving gearing therefor between said shaft and said motor.

222. In a mining machine, a machine frame carrying a motor having a power shaft, cutting mechanism projecting from said frame, an actuating shaft therefor, feeding mechanism on said frame including a feed operating member rotating on a vertical axis and adapted to cooperate with a flexible member in feeding said machine, means for driving the same including a worm wheel rotatable on a vertical axis and a worm rotating on a horizontal axis, and means for driving said actuating shaft for said cutting mechanism and said worm including pinions coaxially arranged on said motor shaft, the driving means for said worm further including a gear driven by one of said pinions on said motor shaft and rotating on an axis parallel to said motor shaft, a shaft coaxial with said gear, a driving pinion coaxial with said third shaft, clutch means reciprocable longitudinally of said third shaft controlling the connection between the gear and pinion coaxial with said third shaft, and a gear coaxial with said worm and meshing with said pinion which is coaxial with said third shaft.

223. In a mining machine, a machine frame carrying a motor having a power shaft, cutting mechanism projecting from said frame, an actuating shaft therefor, feeding mechanism on said frame including a feed operating member rotating on a vertical axis and adapted to cooperate with a flexible member in feeding said machine, means for driving the same including a worm wheel rotatable on a vertical axis and a worm rotating on a horizontal axis, and means for driving said actuating shaft for said cutting mechanism and said worm including pinions coaxially arranged on said motor shaft, there being a frictionally controlled speed reducing gearing between the driving pinion for the feeding mechanism and said worm.

224. A mining machine slidable on a mine bottom comprising a machine frame, cutting mechanism, a motor on said frame actuating

225. A cutting mechanism, a guiding member arranged at one side of the rear end of said frame, a flexible feeding portion extending about said guiding member and having a free end, means cooperating with said flexible feeding portion at a point at the opposite side of said guiding member from said free end and including a winding member rotatable on a vertical axis, and actuating means therefor including fast and slow speed driving mechanism comprising a plurality of rotating elements having frictional controlling means individual thereto and rotating on axes parallel to the axis of said motor.
226. A mining machine slideable on a mine bottom comprising a machine frame, cutting mechanism, a motor on said machine frame actuating said cutting mechanism, a guiding member arranged at one side of the rear end of said frame and rotatable on a vertical axis, a flexible feeding portion extending about said guiding member and having a free end, a winding member rotating on an axis nearer the central longitudinal line of said frame than said guiding member, and driving mechanism therefor including a plurality of coaxial frictionally controlled elements rotatable on an axis parallel to the axis of said motor.
227. In a mining machine, a machine frame slideable on its bottom universally over a mine bottom and including a motor, and means for effecting feeding and guiding of said machine including a vertical shaft having its axis lying substantially in the longitudinal central vertical plane of said machine frame, bevel driving connections between said motor and shaft, a longitudinally extending shaft offset from said longitudinal central vertical plane, driving connections between said shafts including a worm concentric with said first mentioned shaft, a third shaft, driving connections between said second and third shafts including gear elements respectively concentric with each of said shafts, a driving element on said third mentioned shaft, means for clutching the same thereto, a feed operating member adapted to cooperate directly with a flexible feeding member, and driving connections between said driving element and said feed operating member.

228. In a mining machine, a machine frame slideable on its bottom universally over a mine bottom and including a motor, and means for effecting feeding and guiding of said machine including a vertical shaft having its axis lying substantially in the longitudinal central vertical plane of said machine frame, bevel driving connections between said motor and shaft, a longitudinally extending shaft offset from said longitudinal central vertical plane, driving connections between said shafts including a worm concentric with said first mentioned shaft, a third shaft, driving connections between said second and third shafts including gear elements respectively concentric with each of said shafts, a driving element on said third mentioned shaft, means for clutching the same thereto, a feed operating member adapted to cooperate directly with a flexible feeding member, and driving connections between said driving element and said feed operating member.

229. In a mining machine, a machine frame slideable on its bottom universally over a mine bottom including a motor, and means for effecting feeding and guiding of said machine including a vertical shaft having its axis lying substantially in the longitudinal central vertical plane of said machine frame, bevel driving connections between said motor and shaft, a longitudinally extending shaft offset from said longitudinal central vertical plane, driving connections between said shafts including a worm concentric with said first mentioned shaft, a third shaft, driving connections between said second and third shafts including gear elements respectively concentric with each of said shafts, a driving element on said third mentioned shaft, means for clutching the same thereto, a feed operating member adapted to cooperate directly with a flexible feeding member and rotating on an axis substantially in said central vertical longitudinal plane, and driving connections between said driving element and said feed operating member.

230. In a mining machine, a machine frame slideable on its bottom universally over a mine bottom including a motor, and means for effecting feeding and guiding of said machine including a vertical shaft having its axis lying substantially in the longitudinal central vertical plane of said machine frame, bevel driving connections between said motor and shaft, a longitudinally extending shaft offset from said longitudinal central vertical plane and terminating to the rear of said vertical shaft, driving connections between said shafts including a worm concentric with said first mentioned shaft, a third shaft, driving connections between said second and third shafts including gear elements respectively concentric with each of said shafts, a driving element on said third mentioned shaft, means for clutching the same thereto, a feed operating member adapted to cooperate directly with a flexible feeding member and rotating on an axis substantially in said central vertical longitudinal plane, and driving connections between said driving element and said feed operating member.

third shafts including gear elements respectively concentric with each of said shafts, a driving element on said third mentioned shaft, means for clutching the same thereto, a feed operating member, and driving connections between said driving element and said feed operating member.

231. In a mining machine, a machine frame slidable on its bottom universally over a mine bottom and including a motor, and means for effecting feeding and guiding of said machine including a vertical shaft having its axis lying substantially in the longitudinal central vertical plane of said machine frame, bevel driving connections between said motor and shaft, a longitudinally extending shaft offset from said longitudinal central vertical plane and terminating at its rear end rearward of said motor, driving connections between said shafts including a worm concentric with said first mentioned shaft, a third shaft, driving connections between said second and third shafts including gear elements respectively concentric with each of said shafts, a driving element on said third mentioned shaft, means for clutching the same thereto, a feed operating member, and driving connections between said driving element and said feed operating member.

232. In a mining machine, a machine frame slidable on its bottom universally over mine bottom, a vertical shaft having its axis lying substantially in the longitudinal central vertical plane of said machine, a motor, bevel driving connections between the motor and said shaft, a longitudinally extending shaft, driving connections between said shafts including a worm concentric with said first mentioned shaft, a driving pinion on said second mentioned shaft, a gear meshing therewith, a shaft with which said gear is concentric, a driving element loose on said shaft, means for clutching the same thereto, a feed operating member, and driving connections between said driving element and said operating member.

233. The combination with a mining machine slidable on a mine bottom and flexible feeding means therefor operative to feed the same transversely of a mine face during cutting and including advance and receding flexible feeding portions and feed operating means cooperating therewith, of actuating mechanism for said feeding means including a plurality of pairs of driving elements each adapted to produce a different feeding speed, a shaft on which one of the elements of each of said pairs is mounted, and different friction clutches for connecting said last mentioned elements respectively to said shaft, the other elements of said pairs rotating on axes lying in a plane parallel to said shaft.

234. The combination with a mining ma-

chine slidable on a mine bottom and flexible feeding means therefor operative to feed the same transversely of a mine face during cutting and including advance and receding flexible feeding portions and feed operating means cooperating therewith, of actuating mechanism for said feeding means including a plurality of pairs of driving elements each adapted to produce a different feeding speed, a shaft on which one of the elements of each of said pairs is mounted, and different friction clutches for connecting said last mentioned elements to said shaft, the other elements of said pairs rotating on axes lying in a plane parallel to said shaft, and means for driving one of said last mentioned elements including a driving pinion coaxial with the other.

235. In a mining machine, a machine frame slidable on its bottom over a mine bottom, cutting mechanism including a cutter bar projecting at one end of said frame, a motor on said frame comprising a driving shaft rotating upon an axis extending longitudinally of said frame, a feed operating member rotating on an axis lying in a vertical longitudinally extending plane at the opposite end of said frame from said cutter bar and rotatable to effect feeding during cutting a kerf extending transversely of a working face, and means for effecting rotation of said feed operating member at a plurality of speeds including a longitudinally extending shaft, and means driven from said motor shaft for effecting rotation thereof at a plurality of speeds and including a plurality of selectively operable elements coaxial with said shaft.

236. In a mining machine, a machine frame slidable on its bottom over a mine bottom, cutting mechanism including a cutter bar projecting at one end of said frame, a motor on said frame comprising a driving element rotating upon an axis extending longitudinally of said frame, a feed operating member rotating on an axis lying in a vertical longitudinally extending plane at the opposite end of said frame from said cutter bar, and means for effecting rotation of said feed operating member at a plurality of speeds including a longitudinally extending shaft, and means including a plurality of elements coaxial with said shaft, and frictional controlling means also coaxial with said longitudinally extending shaft.

237. In a mining machine, a machine frame slidable on its bottom over a mine bottom during cutting, cutting mechanism carried thereby and projecting therefrom at one end thereof, a motor on said frame, and feeding mechanism at the opposite end of said frame including a feed operating member adjacent the last mentioned end of said frame, and driving mechanism therefor in-

cluding a shaft extending longitudinally of said frame, means including a plurality of elements adjacent the end of said shaft nearer said motor for effecting relatively fast rotation thereof, means including a plurality of elements nearer the opposite end of said shaft for effecting slower rotation thereof, and means for effecting continuous rotation of one element of each of 10 said pairs by power from said motor.

238. In a mining machine, a machine frame 15 slidable on its bottom over a mine bottom during cutting, cutting mechanism carried thereby and projecting therefrom at one end thereof, a motor on said frame and feeding mechanism at the opposite end of said frame including a feed operating member adjacent the last mentioned end of said frame, and driving mechanism therefor including a shaft extending longitudinally of said frame, means including a plurality of elements adjacent the end of said shaft nearer said motor operative when frictionally engaged to effect relatively fast rotation thereof, means including a plurality of elements nearer the opposite end of said shaft operative when frictionally engaged to effect relatively slower rotation thereof, and means for effecting continuous rotation 30 of one element of each of said pairs by power from said motor.

239. In a mining machine, a machine frame 35 slidable over a mine bottom, cutting mechanism including a cutter bar projecting at one end of said frame, and feeding mechanism including a feed operating member adjacent the other end of said frame and adapted on rotation to effect the cutting of a kerf extending transversely of a working 40 face, and driving means therefor including a longitudinally extending shaft, a motor, means including a plurality of gears driven on rotation of said motor and coaxial with said shaft, and means secured in non-rotative 45 relation to said shaft and adapted to cooperate respectively with said gears in the driving of said shaft for causing rotation of said shaft at a plurality of predetermined speeds, and driving connections, between one end of said shaft and said feed 50 operating member.

240. In a mining machine, a machine frame 55 slidable over a mine bottom, cutting mechanism including a cutter bar projecting at one end of said frame, and feeding mechanism including a feed operating member adjacent the other end of said frame, and driving means therefor including a longitudinally extending shaft, a motor, means 60 including a plurality of gears driven on rotation of said motor and coaxial with said shaft, and means secured in non-rotative relation to said shaft and adapted to cooperate respectively with said gears in the

driving of said shaft for causing rotation of 65 said shaft at a plurality of predetermined speeds, and driving connections between one end of said shaft and said feed operating member, said motor being mounted between the opposite end of said shaft and the first 70 mentioned end of the frame.

241. In combination, a wheeled mining machine truck, a mining machine of a type adapted to slide on its bottom over the mine bottom during cutting supported on said truck, a power rotated member on said mining machine, power transmission connections between said member and said truck wheels, said mining machine comprising a motor, and reversing mechanism between 75 the same and said power rotated member.

242. In combination, a wheeled mining machine truck, a mining machine of a type adapted to slide on its bottom over the mine bottom during cutting supported on said truck, a power rotated member on said mining machine, power transmission connections between said member and said truck wheels, said mining machine comprising a motor, and speed changing mechanism between 80 the same and said power rotated member.

243. In combination, a wheeled mining machine truck, a mining machine of a type adapted to slide on its bottom over the mine 85 bottom during cutting supported on said truck, a power rotated member on said mining machine, power transmission connections between said member and said truck wheels, said mining machine comprising a 90 motor, and means operative to effect rotation of said power operated member in one direction at one predetermined speed and in the opposite direction at a different predetermined speed without reversal of said 100 motor between said power rotated member and said motor.

244. In a mining machine, a machine frame, a motor thereon, a truck driving member thereon, variable speed gearing 110 motor driven driving connections therefor including a driving shaft, and a feed operating member having driving connections on said shaft.

245. In a mining machine, a machine 115 frame, a motor thereon, a truck driving member thereon, variable speed gearing motor driven driving connections therefor including a driving shaft, and a feed operating member having driving connections 120 driven by said shaft.

246. A mining machine including, in combination, a feed operating member, a truck driving member, speed changing gearing comprising a plurality of elements selectively operable on rotation of its initial element at a constant speed to effect rotation of its final element at different predetermined 125

mined speeds, and means for selectively operatively connecting either of said members to said final element.

247. A mining machine including, in combination, a feed operating member, a truck driving member, reversing gearing comprising a plurality of elements selectively operative on rotation of its first element in one direction to transmit rotation to its last element in opposite directions, and means for selectively operatively connecting either of said members to said final element.

248. A mining machine including, in combination, a feed operating member, a truck driving member, transmission means thereon including a plurality of elements selectively cooperating on rotation of the initial element thereof in one direction and at a constant speed to transmit rotation to the final element thereof at different predetermined speeds and in different directions, and means for selectively operatively connecting either of said members to said final element.

249. In combination, cutting mechanism, a motor for actuating the same having a power shaft, a wheeled frame, driving mechanism for said wheels including a shaft rotatable upon an axis parallel to the axes of rotation of said wheels and operatively connected to the latter, and driving means for said shaft including a shaft parallel to a line parallel to the power shaft of said motor and means for driving said third mentioned shaft from said motor at a plurality of predetermined speeds including gearing including a plurality of elements rotating at different speeds coaxial with said last mentioned shaft, and friction clutch means for connecting said coaxial gearing elements to said shaft.

250. In combination, cutting mechanism, a motor for actuating the same having a power shaft, a wheeled frame, driving mechanism for said wheels including a shaft rotatable upon an axis parallel to the axes of rotation of said wheels and operatively connected to the latter, and driving means for said shaft including a third shaft parallel to a line parallel to the power shaft of said motor and with its axis in a plane perpendicular to said second mentioned shaft and means for driving said third mentioned shaft from said motor at a plurality of predetermined speeds including gearing including a plurality of elements coaxial with said last mentioned shaft and constantly rotating during running of said motor at different speeds, and friction clutch means alternatively operative to connect said coaxial gearing elements to said shaft.

251. In combination, a wheeled truck, a mining machine supported thereon including a machine frame provided with a projecting cutter bar and enclosing actuating means for said bar including a motor dis-

posed with its power shaft extending longitudinally of said frame and further enclosing at the end of said motor remote from the end of said frame from which said cutting mechanism projects a shaft parallel to a line parallel to the power shaft of said motor, gearing actuated by said motor for driving said last mentioned shaft and including a plurality of elements spaced longitudinally of said shaft but coaxial therewith and rotating at different predetermined speeds during operation of said motor and friction clutch means for selectively connecting said elements to said shaft, and operative connections between said second mentioned shaft and the wheels of said truck.

252. In combination, a wheeled truck, a mining machine supported thereon including a machine frame provided with a projecting cutter bar and enclosing actuating means for said bar including a motor disposed with its power shaft extending longitudinally of said frame and further enclosing at the end of said motor remote from the end of said frame from which said cutting mechanism projects a shaft parallel to a line parallel to the power shaft of said motor, gearing actuated by said motor for driving said last mentioned shaft and including a plurality of elements spaced longitudinally of said shaft but coaxial therewith and rotating at different predetermined speeds during operation of said motor and friction clutch means for selectively connecting said elements to said shaft, and operative connections between said second mentioned shaft and the wheels of said truck including a transversely disposed shaft and a chain and sprocket connection between the latter and said wheels.

253. In combination, a mining machine slidable upon a mine bottom during cutting and including a driving motor, friction controlled feeding mechanism driven by said motor and motor driven truck driving mechanism driven by the same end of said motor driving said feeding mechanism including a truck driving element on said machine and a friction mechanism on said machine controlling the same, a wheeled truck adapted to carry said machine during transport, and operative connections between said truck driving element and said truck wheels.

254. In combination, a mining machine slidable upon a mine bottom during cutting and including a driving motor, friction controlled feeding mechanism driven by said motor, and motor driven truck driving mechanism driven by the same end of said motor driving said feeding mechanism including a truck driving sprocket rotatable on a transversely extending axis and a friction mechanism on said machine controlling the same, a wheeled truck adapted to carry

said machine during transport, and a friction connection between said sprocket and said truck wheels.

255. A mining machine slideable on a mine bottom comprising a machine frame, flexible feeding means including advance and receding portions extending in opposite directions from the opposite ends of the frame, and feed operating means for feeding the machine in opposite directions at different speeds relative to said flexible feeding means and at a predetermined cutting speed along the receding portion, said means including a fast feed friction and a separate slow feed friction.

256. The combination with a mining machine slideable on a mine bottom and flexible feeding means therefor, feed operating means operative to propel the machine in opposite directions relative to the flexible feeding means including a friction device connectible therein when feeding in one direction, a separate friction device connectible therein when feeding in the opposite direction, and supplementary mechanical reverse effecting means.

257. In combination, in a mining machine slideable on a mine bottom during cutting and means for feeding the same operable to effect the cutting of kerfs in opposite directions including flexible feeding means, feed operating means cooperating therewith, driving means for said feed operating means including means connectible therewith to effect drive thereof, a motor, and means between said motor and said connectible means to effect rotation of the latter at different speeds, said last mentioned means including separate friction mechanisms at said different speeds.

258. The combination in a mining machine slideable on a mine bottom during cutting, with a feed operating member adapted to cooperate with flexible feeding means, and a motor, of variable speed reduction mechanism between said member and said motor operative to transmit rotation from the latter to the former at different speeds in opposite directions while said motor runs in one direction, and friction clutch mechanism interposed between said reduction gearing and said feed operating member during either drive thereof adjustable at will during the operation of said feed operating member.

259. The combination with a mining machine slideable on a mine bottom during cutting, flexible machine feeding and guiding means, a feed operating member adapted to propel said mining machine transversely of a mine surface during lateral cutting, a motor, variable speed reduction gearing connecting said motor and member, and friction clutch mechanism interposed between said reduction gearing and said feed operating member adjustable at will during the operation of said feed operating member.

260. The combination with a mining machine slideable on its bottom on a mine bottom, of a motor, reduction gearing driven thereby, a feed operating member adapted to cooperate directly with flexible feeding means, a truck driving member, and means for selectively connecting either of said members to said gearing for rotation thereby at different predetermined speeds.

In testimony whereof I affix my signature.

MORRIS P. HOLMES.
